UNITED STATES PATENT OFFICE.

WALTER WRIGHT, OF SAN FRANCISCO, CALIFORNIA, ASSIGNOR, BY MESNE ASSIGNMENTS, TO UNDERWOOD COMPUTING MACHINE COMPANY, A CORPORATION OF NEW YORK.

COMPUTING ATTACHMENT FOR TYPE-WRITERS.

1,160,102.

Specification of Letters Patent.

Patented Nov. 9, 1915.

Application filed April 1, 1907, Serial No. 365,886. Renewed July 1, 1909. Serial No. 505,492.

To all whom it may concern:

Be it known that I, WALTER WRIGHT, a citizen of the United States, residing at San Francisco, in the county of San Francisco 5 and State of California, have invented new and useful Improvements in Computing Attachments for Type-Writers, of which the following is a specification.

The object of the present invention is to 10 provide a computing attachment for type-writing machines, which can be attached with comparative ease to any of the standard forms of such machines, which will be simple and inexpensive in construction, 15 which will add at the same time a considerable number of separate and independent columns of figures corresponding with numerals written in similar columns by the typewriter, or, when desired, will perform 20 the operation of subtraction in any column or at any part of said column.

In the accompanying drawings, Figure 1 is a front view of a typewriting machine equipped with my improvement; Fig. 1^a is a 25 vertical transverse section through one of the key levers; Fig. 2 is a detail side view of one of the shutters; Fig. 3 is a side view showing one of the arms by which the computing carriage is moved with the typewriter carriage; Fig. 4 is an enlarged front view, partly broken away, of the operating mechanism at one end of the machine; Fig. 5 is a longitudinal sectional view of the transmitter carrier and the controller, taken 30 on the line 5—5 of Fig. 6; Fig. 6 is a side view of the controller; Fig. 6^a is a view of the other side of the controller; Fig. 7 is an enlarged view of one of the pins in the controller; Figs. 8 and 9 are side views of the 35 escapement wheel in different positions; Figs. 10 and 11 are front views of the same in the corresponding positions; Fig. 12 is a broken enlarged front view of computing and figure wheels and the mechanism immediately coöperating therewith; Fig. 13 is a transverse section of the same looking from the left; Fig. 14 is a similar view looking from the right; Fig. 15 is a front view of the locking lever and the releasing lever; Fig. 16 is a horizontal section on the line 16—16 of Fig. 14; Fig. 17 is a detail front view showing one of the computing wheels and a primary transfer wheel adapted to be 45 engaged thereby, detached; Fig. 18 is a sectional view of the computing wheels; Fig. 50

18^a is a perspective view of a transfer wheel; Fig. 19 is a broken longitudinal view of the shaft carrying the figure wheels; Fig. 20 is a cross sectional view of the same; Fig. 21 is a side view of one of the figure wheels; Fig. 22 is a plan view of said shaft; Fig. 23 is a side view of the internal parts of said shaft showing the teeth withdrawn; Fig. 24 is a broken side view of the computing shaft, the tubes being shown in section; Fig. 25 is a cross-section of said shaft; Fig. 26 is a broken plan view of the same; Fig. 27 is an enlarged side view of the error-correcting knob; Fig. 28 is a sectional view of the same; Fig. 29 is an end view of the computing attachment; Fig. 30 is a front view of part of the driving mechanism therefor; Fig. 31 is a view of an end plate of the attachment, viewed from the inside; Fig. 32 is an end view of the attachment to the computing carriage, for effecting a transfer from one wheel to the next; Fig. 33 is a broken front view of the same; Fig. 34 is a detail side view of the partitions in the computing carriage; Fig. 35 is a front view of the same; Fig. 36 is a broken detail view of the device for effecting the subtraction; Fig. 37 is a detail sectional view of a part of the controller. Fig. 38 is a diagrammatic side elevation of the well-known Monarch typewriting machine with my improvements connected thereto.

Connection.—Referring to the drawings, 1 (Fig. 1) indicates the frame of a typewriting machine, which may be of any standard construction, but, for the purpose of illustration, is herein shown as a "Monarch" machine. Secured upon the right hand side of the frame is a plate 2 having an extension or arm 3, at the end of which is supported a vertical plate 4. Secured upon the extension 3 is a ring 5 through which pass wires or rods 7 attached at their left hand end to bell crank levers 8, to the other arms of which levers 8 are attached links 9, which pass through apertures 10 in a shift bar 11. Each link 9 is formed at its lower end into a hook 12, which by the movement of the shift bar 11, is adapted to be moved into an aperture 13 in a collar 15 secured upon the lever 14 of one of the numeral keys 16 of the machine. By sliding the bar 11 to the left, all of said links can be caused to engage their respective apertures 13, and, by this means, the computing mechanism 105

can be made ready for operation. To move said shift bar 11 to the left, there is provided a three-armed lever 17 attached to said shift bar and also to two key stems 18 and 19. By depressing the stem 18, the counting attachment is operatively connected with the numeral keys, and by depressing the stem 19, it is disconnected therefrom.

- 10 *Controller.*—The connecting wires 7 are attached at their other ends to small bell crank levers 20, (Figs. 4, 5,) which are pivotally mounted on the ring 5. By the movement to the left of one arm of a bell 15 crank lever 20, the other arm of said lever is moved against the end of a jack or slideable transmitter rod 22, said rods sliding in apertures 23 in a cylindrical transmitter carrier 24 supported on the extension 3, the 20 left end of said rods being bent outward at 29 and adapted to slide in slotted guide rods 27, around which guide rods are coiled compression springs 28 tending to press said rods 22 to the left and toward the center of 25 carrier 24, the latter movement being limited by pins 26 which close the ends of the slots in the rods 27. Thereby, by the movement of any numeral key, the corresponding transmitter rod 22 is pushed to the right. 30 Since the rods 22 slide in grooves upon the face of the transmitter carrier, and since their bearings in the carrier are sufficiently short and loose, they can swing outward when impinged upon by the levers 20 in 35 their outward movement, and thus permit the levers 20 to return.

Upon a shaft 25, having a bearing in the plate 4, is secured a primary escapement wheel or rotary controller 30, which is 40 formed with a circular series of ten holes or slideways 31 (Fig. 6), in which are loose escapement teeth or bolts 32 of greater length than the holes, their ends on the left being adapted to abut against the inner sides 45 of the radial arms 33 of small detents in the form of bell crank levers 34 pivoted in slots formed in a wall 30' in said controller, the detent arms 36 of said bell crank levers being pressed downward by a circular helical 50 or coiled spring ring 37 around all of said arms 36. By this means the radial arms 33 of said bell crank levers are all extended leftwardly or away from said controller. When any one of the numeral keys is actuated, and thereby the corresponding transmitter rod 22 is pushed to the right, said rod strikes the radial arm 33 of the bell crank lever 34 which has been brought opposite thereto, and moves said arm to the 55 right, the end of the controller being recessed below said wall 30' to allow said arms 33 to move freely thereinto when so struck. Thereby, the bell crank lever 34 pushes said bolt 32 to the right so that it projects out of 60 the controller. The bell crank lever 20 con-

tinues past or trips off from the end of the rod 22, whereupon said rod immediately returns by the action of the spring 28, freeing the bell crank lever 34, so that the controller is free to rotate. The bell crank lever 20 70 can freely return on the release of the numeral key, since the end of the rod 22 is moved radially outward by the end of said bell crank lever as it passes. The controller is formed with a circumferential groove 65 75 intersecting the apertures 31, so that the ends of the arms 36 bear down on the bolts 32; said bolts being formed with recessed portions or necks 68 to receive said arms. The movement of each bolt is limited in one 80 direction by the plate 4, and in the return direction by the arm 33 of the bell crank lever 34, the radial arm 33 of which is prevented moving to the left by the abutment of the arm 36 against the neck 68 of the bolt. 85 The object of so extruding one of the bolts carried by the controller on the depression of a numeral key is to control the extent to which a computing shaft 35 is rotated. I will now describe the mechanism for rotating said shaft. Said shaft 35 extends between the plate 4 and a frame 38 secured on the left hand side of the frame of the typewriting machine. On the end of said shaft 90 extending through the plate 4 is a bevel gear 39, which is engaged by a bevel gear 40 on a shaft 41 carrying a bevel gear 42 meshing with a bevel gear 43 on the shaft 25, said shaft being driven by a gear wheel 44 thereon meshing with a gear wheel 45 on a stud shaft also carrying a bevel gear 46 meshing with a bevel gear 47 on a power shaft 49, which is under torsional strain from the constantly applied force of driving mechanism hereinafter described. On account of 105 the connection of the shaft 25 with the power, the controller 30 tends to rotate whenever permitted to do so by certain feeding or releasing mechanism. This releasing mechanism is operated by the depression of 110 a numeral key as follows:—Suspended by links 50 from the frame of the typewriting machine is a universal bar 51, which has a number of pins 52, each adapted to be engaged by a corresponding bell crank lever 115 8, so that, on the operation of a numeral key, the corresponding pin 52 being engaged by its bell crank lever, the universal bar is moved to the left. The end of said universal bar on the right is connected to a crank 120 arm 53 on the shaft 54 mounted in bearings 55 on the plate 4; and on said shaft is carried an escapement device, which comprises two dogs or disks 56, 57, having cut out from their edges recesses or openings 58, 59 125 (Figs. 10, 11) offset from each other, for the purpose of permitting and controlling the passage through them of one of a series of lugs or teeth 60, on a secondary escapement wheel 61, (Figs. 8, 9) four of such lugs be- 130

- ing here shown. Said wheel 61 is on a shaft 62, which extends through the plate 4 and carries a star wheel or pinion 63 having the same number of points or teeth as there are 5 lugs 60 on the escapement wheel 61, these points being adapted, by the rotation of said pinion, to be brought into the path of one of the teeth or bolts 32 extruded from the controller by the operation of a numeral key.
- 10 Previous to the depression of any numeral key, another bolt 32 which has been so extruded, by the next preceding depression of a numeral key still remains extending out from the controller and in engagement with 15 a point of the star wheel 63, the star wheel being held from rotating by the pressure (hereinafter explained) of a lug of the secondary escapement wheel 61 against the first of the escapement dogs 56 as in Figs. 8 and 20 10. Upon the depression of a numeral key, the crank 53 is moved to the left, which causes the escapement or dog device to rotate through a small angle into a position to permit the lug 60 on the secondary escapement wheel to pass through the opening 58 in the edge of the first disk. This it immediately does, as shown in Figs. 9 and 11, being actuated so to do by the pressure against the pinion of the bolt 32 which was 25 last operated. (Fig. 6) and this pressure, again, is produced by the force constantly applied to the power shaft 49 and transmitted to the controller shaft 25. Consequently, as regards the computing, the depression of the key accomplishes two results, first, it extrudes from the controller 30 a bolt 32 corresponding to the particular numeral key depressed, and, second, it moves the secondary escapement wheel a slight distance, into a position so that the tooth thereof which was in engagement with the first disk 56 is now between the two disks 56 and 57 of the escapement device; and these parts remain in this position until the key is released by raising the finger. As soon as the operator's finger is raised to release the key, a spring 64 moves the universal bar 51 to the right, thereby moving the crank 53 to the right, and the upper portion of the escapement device to the right, and thereby moving the opening 59 in the second disk 57 of the escapement device into such position that the tooth 60 upon the secondary escapement wheel 61 can pass through it.
- 45 The secondary escapement wheel being now perfectly free to rotate, the star wheel 63 no longer resists the pressure from the previously operated bolt 32, but permits the primary escapement wheel or controller to 50 rotate, the secondary escapement wheel 61 also rotating through nearly a quarter of a revolution, until the next tooth 60 thereon brings up against the first disk 56 of the escapement device, which is now in such a 55 position that the tooth cannot pass through the opening 58 and consequently now presses against said disk 56 as in Figs. 8 and 10. With this movement of the escapement device the pinion 63 also moves a quarter of a revolution, so that the next point thereof arrives at such a position as to arrest the bolt 32 carried by the controller, and which has been extruded therefrom by the depression of the numeral key just operated. Corresponding to a given extent of rotation of the controller, the computing shaft 35 is also rotated, and, as hereinafter described, it imparts rotation to the computing mechanism. As the controller 30 rotates, the bolt 32 which previously engaged the pinion 63, and 60 has been permitted to pass the same, engages the face of a wedge 66 extending inwardly from the plate 4, and is, by the said wedge, returned to its normal position in the controller ready for subsequent use. The 65 two disks 56 and 57 are, by means of set screws 56', 57', secured upon the shaft 54 adjustably, to permit the escapement to be used with any particular action of the typewriter, so that the controller can be released 70 either on the downward stroke of the key, or on the return thereof.
- Computing mechanism.*—The computing shaft 35 rotates but has no longitudinal movement. Secured to said computing shaft 75 are one or more teeth 70, (Figs. 14, 24, 25, 26) two being here shown. Surrounding the shaft 35 are two tubes 71, one on each side of the central teeth 70, which are provided primarily for the purpose of reducing the 80 friction of said shaft and permitting it to turn more easily, and on said tubes are supported a series of computing wheels 72, corresponding to letter spaces of the typewriting machine. These computing wheels move 85 with the typewriter carriage 82 to the left and thus pass in succession over the teeth 70 extending from the computing shaft; and of said computing wheels only that one immediately over or around said part of the 90 shaft carrying said teeth is directly operated by the rotary movement of said shaft. Each computing wheel is formed as an internal gear wheel having ten recesses or notches 73, and, as the typewriter carriage moves to the 95 left, a pair of opposite notches, on each wheel 72 in succession, are brought into engagement with the two teeth 70 on the computing shaft, no matter in what angular position said teeth were left by the last preceding operation. Consequently, when the computing shaft 35 is rotated, by the mechanism heretofore described, upon the depression or release of any numeral key, the computing wheel which is in engagement with 100 the teeth 70 of said shaft is correspondingly rotated. Said computing wheel is formed with external gear teeth 74, which mesh with a pinion 75, which in turn mesh with gear teeth 76 formed at the side of a figure 105 110 115 120 125 130
- 60 65 70 75 80 85 90 95 100 105 110 115 120 125 130
- 65 70 75 80 85 90 95 100 105 110 115 120 125 130

wheel 77, the face of said wheel carrying the figures 0 to 9. Consequently, said figure wheel is given a rotation corresponding in extent to that of the computing shaft 35, 5 and to the particular numeral key depressed.

A casing 78 is provided, (Fig. 12) covering the figures of all the figure wheels 77 except one row, the figures of which indicate the result of the computation made. For instance, if any figure wheel stands so that the figure "7" is displayed, and then the numeral key "2" is depressed, then, upon the depression or release of said key, said figure wheel is advanced so that the figure "9" is displayed. The carriage 79 which carries the computing wheels 72 is separated into compartments by vertical partitions 80 consisting of thin plates which pass between adjacent computing and figure wheels, and 15 they brace and strengthen the computing carriage 79. The carriage is provided with gear wheels 108 (Fig. 1) which run on a rack 81, and is advanced with the typewriter carriage 82 by means of arms 83 extending 20 forward from the typewriter carriage and carrying fingers 84 pivoted on the ends of said arms, which, when moved down, engage the ends of the computing carriage 79, and move it with the typewriter carriage. When 25 said fingers are moved up and thrown back, as shown in dotted lines at Fig. 3, the computing carriage 79 can be longitudinally moved independently of the typewriter carriage.

30 *Transferring.*—In order to carry on from one wheel to the next when a number is added to the previous number on said wheel so as to make the total greater than nine, there is formed at one side of each computing wheel 72 a lug or tooth 85, (Figs. 13, 17, 18,) which, in the rotation of the computing wheel, is brought into engagement with a tooth 86 on a primary transfer wheel 88 loose on a shaft 88', said tooth 85 being 35 adapted to partly turn said wheel 88. The teeth of this primary transfer wheel engage teeth 89, ten in number, on the next computing wheel 72 to the left, and advance the same one-tenth of a revolution. 40 However, this transfer wheel does not, by its mere movement due to the advance of the lug 85 on the computing wheel 72, impart said advance, but auxiliary mechanism is provided to completely accomplish 45 this result. Such mechanism is preferred because it is found that, without such auxiliary mechanism, when a large number of such wheels stand at "9," or in the position in which the transfer is to be effected to the 50 wheel of the next higher denomination, and it is necessary that all of said transfers should be made at once, which they would necessarily do if made directly and without such auxiliary mechanism, the resistance 55 caused by having to transfer so many wheels

simultaneously is very great, causing a drag in the operation of the computing mechanism. Such a condition, although occurring very rarely, is possible, and such tardiness of operation might vitiate the accuracy of 70 the machine. As a means of avoiding this objection, I provide an auxiliary mechanism the main element of which is a secondary transfer shaft 90. For convenience, the mechanism for operating this shaft will 75 be described later. For the present it is sufficient to say that said transfer shaft rotates in the direction shown by the arrows in Figs. 13 and 14 when the operation is that of addition, and in the opposite direction when the operation is that of subtraction. The transfer is therefore effected in 80 the following manner: When the lug 85, moving in the direction of the arrow shown in Fig. 13, has made a complete revolution 85 with the computing wheel 72 upon which it is formed, it impinges against the rear side of the narrow tooth 86 on the wheel 88, which, as already stated, is loose upon the shaft 88'. In moving through one-tenth of 90 a revolution, it advances said wheel 88, so that a wide tooth 86', next but one in advance of said narrow tooth, is moved down into a position midway between two pairs of longitudinal ribs 90', formed on a cylinder 90" secured upon the secondary transfer shaft 90, said ribs coöperating with the tooth 86' in the manner of gear teeth. Since 95 the secondary transfer shaft 90 revolves rapidly, for the reason hereinafter described, the leading rib of the next following pair of ribs 90' will impinge against the rear side of the wide tooth 86', and will complete the advance of the primary transfer wheel. As said primary transfer wheel 100 88 is thus advanced, the wide tooth 86' immediately following the narrow tooth 86 which was so actuated by the lug 85, passes between the somewhat wide teeth 89 of the 105 next computing wheel 72 to the left, and, by engagement with said teeth, advances said computing wheel through one-tenth of a revolution, then assuming the position shown in Figs. 13 and 14, in which the next narrow tooth 86 is then in position to be engaged by the lug 85 after another complete revolution of the corresponding computing wheel.

110 The reason why the ribs on the secondary transfer cylinders 90" are made in pairs, is to provide for the operation of subtraction 120 as well as addition, the leading rib 90' in either direction of motion of said cylinder being the operating rib.

I will now describe in detail the manner 125 in which the secondary transfer shaft 90 is rotated. However, the invention is not limited to the specific means here shown for accomplishing this purpose. Said transfer shaft extends (Fig. 1) between the two end 130

plates of the carriage 79, parallel with the computing shaft. This shaft 90 is rotated with the movement of the computing carriage 79, and for this purpose, said shaft has 5 secured on each end bevel gears 96, Fig. 33, and these gears 96 mesh with bevel gears 97 on transverse shafts 98, carried by the ends of the computing carriage, and carrying on their rear ends pinions 99, Fig. 32, which 10 mesh with gear wheels 100, Figs. 1, 32 and 33, which are loose on transverse shafts 101, also carried by the computing carriage. On the front ends of said shafts 101 are secured the gear wheels 108 which mesh with the 15 stationary rack 81. As the computing carriage travels to the left, the gear wheels 108, being thereby rotated in the direction of the arrow in Fig. 33, rotate the shafts 101. Secured to said shafts 101, in front of the 20 gear wheels 100, are notched wheels 104, and on the faces of the wheels 100 are pivoted the double pawls 105 having central arms 106, the ends of which are pressed, to one side or the other, by flat springs 107, 25 secured at 210 to the faces of the wheels 100. Each spring 107, therefore, tends to maintain one of the noses 105' of its corresponding pawl in engagement with a notch of the corresponding wheel 104. But by reason of 30 said nose 105' being to one side of the pivot of the pawl 105, said pawl operatively engages said notched wheel 104 when the latter is rotating in one direction only. The two pawls 105 are oppositely arranged, so 35 that when either operatively engages its notched wheel, the other may be adjusted to slip over its notched wheel without engaging. Thus, supposing that the computing carriage is traveling to the left, and 40 the parts are in the position shown in Fig. 33, the pawl 105 will operate to connect the wheel 100 with the wheel 104, imparting a right handed rotation to the secondary transfer shaft 90, looking along said shaft 45 to the left; but the pawl 105 at the left end of the carriage will be adjusted to inoperative position. When the carriage returns, the pawl 105 on the right will be inoperative, and that on the left operative, and it 50 will be readily seen that the connection is such as to rotate the secondary transfer shaft 90 in the same direction as before. By placing the pawls in the Fig. 1 position, the carriage 79 may be locked against travel 55 in letter spacing direction. By now shifting either one pawl or the other from the Fig. 1 position, the mechanism will be set for either addition or subtraction as the case may be. It may be here stated that the 60 object of using two-nosed pawls is to employ the secondary transfer shaft 90 for subtracting, when desired, as will be more fully hereinafter explained. When it is desired to so use it, the relative positions of the pawls 65 105 are changed from Fig. 1, so that the

other nose of one pawl is now pressed by the spring against the notched wheel 104. Upon thereafter shifting both pawls the effect is produced of turning the secondary transfer shaft 90 in the reverse direction.

If the transfer or carry-over shaft 90 has three pairs of teeth, as shown, the gears 99 and 100 should be proportioned to give the shaft 90 a third of a revolution at each letter-feeding movement of the carriage, which in typewriting practice varies from $\frac{1}{16}$ to $\frac{1}{8}$ of an inch. The shaft 90 is shown diagrammatically. In its normal position, a line drawn through the axes of 88' and 90 should pass midway between the teeth in 80 a pair on the remote side of 90 from 88'. So the coupling tooth 86 normally should occupy a position in direct line with the axes of 35 and 88', so as to have an equal movement in either direction under the thrust of 85 starting tooth or lug 85.

It has already been stated that the computing wheels are arranged to correspond with the typewriting spaces of the typewriter. They are, however, arranged in 90 groups of three, corresponding to three such typewriter spaces, each group being spaced from the next adjacent group an interval corresponding with the fourth such typewriter space. The intervening space between the figures of the figure wheels 77 may be occupied by a period or comma or may be left blank, but such intervening space in either case serves to divide such figures into 95 groups of three. In other words, the whole line of figures displayed by the machine will be divided into groups of three, each group being spaced from the next adjacent group by an interval not more than one typewriter space, and the three computing wheels of a 100 group corresponding to three such typewriter spaces. This arrangement enables the operator to insert commas or periods at the end of each group of three figures just 105 in the same way as in ordinary typewriting, so that the hundreds are shown plainly divided from the thousands, and the hundreds of thousands from the millions, and so on. At the same time the construction is such as 110 to permit of carrying from the computing wheel on the left of any group to the computing wheel on the right of the next adjacent group to the left, through the intervening space between the two groups. For this purpose, every third computing wheel 115 72^x and the corresponding figure wheel 77, are each made of an excessive width, as compared with the other two computing or figure wheels, so as to extend across said intervening spaces between the groups of 120 figure wheels, and the primary transfer wheels 88^x corresponding to the transfer wheels 88 are also made correspondingly wide. An extra wide computing wheel 72^x is shown in detail in Fig. 18, having a wide 125 130

flange 72', and is also seen at the sides of Fig. 16, and an extra wide primary transfer wheel 88^x is shown in detail in Fig. 18^a. Said wide primary transfer wheel differs 5 only from the narrow transfer wheel in that, instead of each wide tooth of the latter, the former has two separate teeth 86^x, 86^y, in axial alinement with each other, the difference being one of form only. In the case of 10 the narrow wheel 88, these two teeth join each other and form one wide tooth 86', whereas, in the case of the wide wheel, the teeth are separated from each other a distance corresponding to a typewriter space. The 15 extra wide computing wheels 72^x differ from the other two computing wheels 72 only in having an extra deep crown flange 72', which is made of sufficient depth to occupy the space between adjacent groups. It may 20 be here observed that when the teeth 70 upon the computing shaft 35 arrive at the space immediately within this deep crown flange 72', they are inoperative to turn any computing wheel. It therefore follows that, 25 as the typewriter carriage and computing carriage move successively through typewriter spaces, the teeth 70 of the computing shaft 35 are successively brought into three operative positions, in which they can engage 30 computing wheels, and then, at the fourth such movement, into a position in which they are inoperative, having arrived at the space within the crown flange 72' of a wide computing wheel. From this it results 35 that should the operator strike a numeral key in the wrong position, that is, out of one of the columns of figures, this would cause no change in the figures, for, although the computing shaft 35 would be rotated there- 40 by, the teeth 70 of said shaft would be revolving in a position in which they could not engage any computing wheel.

Each partition 80 may be formed with a curved rib 109, Figs. 12, 34 and 35, which 45 at the part appearing through the cover strip in the casing 78, may be formed with a period or a comma to correspond with the point of separation into groups of three wheels. The result is that the entire row of 50 characters appearing through the cover strip is divided into groups of three numerals, the groups being separated by one typewriter letter space. It will have been perceived that in the present invention a considerable 55 number of separate and independent columns may be added at the same time. But, when any part of a group of computing devices is not being used, the corresponding wheels will show the numeral "0" 60 through the cover strip, and therefore, in order to avoid uncertainty as to the termination of the figures making the total, there are provided small shutters 110, Figs. 1 and 3, which can slide on a rod 111 to cover 65 either the space intervening between two

groups, or the last figure wheel of a group when computing cents, and also to indicate the beginning of the figures which form the respective columns.

Locking mechanism.—A most important 70 consideration in regard to computing mechanism is accuracy. The computing wheels should not by any possibility move from their proper position except when positively advanced by mechanism for that purpose. 75 To insure this I provide the following locking mechanism: For each computing wheel there is provided a locking lever 112, (Figs. 13, 14, and 15) all of said levers being pivotally mounted upon a bar 113 extending 80 longitudinally between the ends of the computing carriage. Each lever has a recess or notch 114 which is adapted to engage any one of the teeth 89 formed upon the corresponding computing wheel 72. Said lever 85 112 is normally pressed against the primary transfer wheel by means of a spring 115, and the end of the same arm is formed with a beveled head 116 which, when the primary transfer wheel 88 begins to rotate, is moved outward by the tooth 86' of said wheel, and so moves the locking lever from its locking position. Said transfer wheel is locked against accidental rotation by means of a spring 117 having a hump 118 which passes 90 between any one of the pairs of teeth on said transfer wheel.

At the depression of a numeral key, the arm 206 rises, Fig. 4, permitting spring 131, Fig. 29, to lift rod 129 and rock up arm 100 128 idly. Upon the return of the key, arm 206 forces down the rod 129, pulling down arm 128, striking the trip 126 on arm 125, and swinging down the latter until the tip of arm 128 passes by the trip 126. However, 105 arm 125 is held down by means of latch 136 (see Fig. 31), which holds up arm 134 (connected through 133, 132 and 122 to said arm 125), said arm 134 having been elevated above said trip 136 by the action of arm 110 128 in depressing arm 125, and said latch having thereupon been snapped by spring 138 under said arm 134. This latch will be released in the manner described, by the protruded index pin 32 striking the same, 115 whereupon the dog 112 will be permitted to relock the actuated computation wheel. Upon the succeeding depression of a numeral key, the arm 128 will rise idly, slipping past the trip 126, which is snapped into 120 position again by the spring 127.

Releasing mechanism.—It is, of course, necessary to release said locking lever 112, in order to rotate the computing wheel 72, and for this purpose there is provided a 125 finger 119, (Fig. 15) which is pivoted in a fork 120 on a collar 121 secured upon a longitudinal rock shaft 122 which extends between the plate 4 and frame 38 and has bearings therein. Said collar 121 is secured 130

in such position on said shaft 122 that it lies in the same vertical plane as the teeth 70 on the computing shaft 35. Consequently, it acts only upon the locking lever corresponding to the computing wheel which, having arrived at that point of the shaft 35, which carries the teeth 70, is in position to be rotated by the turning of said shaft. The end of the finger 119 lies immediately 5 behind a releasing arm 123, extending outwardly and rearwardly from said lever 112, and, upon the rocking forward of said finger 119, said arm 123 is also rocked forward, moving the notch 114 in the lever 112 10 out of engagement with a tooth 89 on the computing wheel 72 and releasing said wheel. To so rock said finger 119 forward there is secured upon the end of the rock shaft 122, adjacent the right side of the 15 plate 4, an arm 125, (Fig. 29) upon which is pivoted a stop 126, which is normally depressed by a spring 127. Opposite said stop 126 is arranged a pivoted arm 128 from which depends a hanger rod 129 having a 20 pin 130 adapted to be engaged by a crank 206 on the shaft 54. On the depression of a numeral key, said crank 206 is raised and releases the hanger rod 129, which rises under the action of a spring 131, the arm 128 25 at the upper end of said rod likewise rising and escaping past the end of the pivoted stop 126, which then drops back into place under the action of the spring 127. Then upon release or depression of the numeral 30 key, the hanger rod 129 again descends, so that the arm 128 depresses the stop 126, and rocks the shaft 122, moving the finger 119 forward, withdrawing the locking lever 112. To maintain said locking lever in its position 35 of release, there is secured on the rock shaft 122, adjacent the left side of the plate 4, a rearwardly extending arm 132, from which depends a hanger rod 133, attached at its lower end to a pivoted arm 134, pulled 40 down by a spring 135. A latch 136 is pivoted at 137 on the plate 4, and when the arm 134 is raised by the rocking of the shaft 122 to actuate the releasing means to withdraw the locking lever 112, the upper end 45 of the latch 136 is adapted to be pressed by a spring 138 beneath the end of said arm 134, holding it up, and maintaining the locking mechanism inoperative (Figs. 29 and 31). The locking lever 112 is held in the 50 position in which the computing wheel is unlocked, until the controller 30, carrying the bolts 32, has almost completed its movement due to the release of the numeral key, and the bolt 32 which has just been extruded 55 from the controller has almost arrived at the star wheel stop 63, the end of its course. Just before it so arrives, said bolt strikes the lower end of the latching lever 136 and forces it outward, thereby swinging its upper end away from the end of the arm 134, 60 and permitting the rock shaft 122 to return to its original position, which it immediately does. This only takes place when the controller 30 has arrived at the position of rest, Figs. 6 and 29, and immediately the 65 notch 114 in the locking lever 112 engages the tooth 89 opposite thereto of the computing wheel 72, and insures that the figures of the figure wheels 77 will be in exact alignment. 70

The construction of the computing mechanism permits the use of the ordinary typewriter escapement in which the advance of the typewriter takes place on the release of the numeral key (although, if desired, the 75 reverse escapement could be used for the typewriter carriage). The computing mechanism is operated after the typewriter key has been depressed and while said key is returning to original position. The typewriter carriage is let off at the last part of the return stroke of the typewriter key. As the key rises, the computing wheel 72 which at the moment is at the printing point is turned by the master wheel 70, this occurring before the carriage starts, or at least before 72 is out of mesh with 70. The finger 119, which releases the locking lever 112, is pivoted, so as to permit of a lateral swing when engaged with the locking lever, the 80 amplitude of this swing being the same as a typewriter letter space. By so pivoting this finger 119 the releasing arm 123 is permitted to engage said finger 119, notwithstanding the movement of the carriage (Fig. 15). 85 The locking levers of the computing wheels which may have been already acted upon by the releasing finger 119, are released only at the instant that the transfer is made from the wheel 72 corresponding to the next lower 90 denomination, and this is effected by the same movement of the primary transfer wheel 88 which advances the computing wheel 72 one-tenth of a revolution, this being accomplished by a wide tooth 86' of 95 the transfer wheel 88 engaging the head 100 116 of the lever 112 of the corresponding computing wheel and pushing said lever 112 away from said computing wheel 72. 105

Resetting mechanism.—In order to reset 110 all the figure wheels 77 to zero, the following mechanism is provided: Said wheels turn loosely upon a tube 140 (Figs. 19, 23,) having a longitudinal series of apertures 141, through which extend teeth 142 formed upon 115 a flat bar 143. Said bar slides between two approximately half-round rods 144 connected by pins 145, which pass through oblique slots 146 in the flat bar 143. The rods 144 are connected at one end with a knob 147. By 120 pushing said knob to the left, said pins, acting in said slots, push the flat bar 143 outward, so that the teeth 142 project beyond the apertured tube, as in Figs. 19 and 20. Each tooth is then in position to engage a 125 130

radial lug 148 of the figure wheel 77 extending into a cavity formed therein. But before said wheels can be reset to zero they must be unlocked. This is effected by means 5 of an eccentric shaft 149 carrying a small knob 150 on its end projecting through the right-hand side of the casing 78, (Figs. 13, 14 and 20), said eccentric bearing against an upwardly extending arm 151 of each 10 locking lever 112. Upon turning said knob, the movement of the shaft 149 causes the wide part of the eccentric to engage said arms 151, and thereby move the locking levers 112 out of engagement with the computing 15 wheels 72, permitting said computing wheels and figure wheels 77 to turn freely. Then, to reset to zero, the knob 147 is first pushed to the left, and then rotated, whereupon the teeth 142 are first projected 20 and then rotated, until they strike the lugs 148, which happens sooner or later with the several wheels 77 according to the position in which they have been left by the previous computation, and since these lugs 148 extend 25 from all the figure wheels 77, the effect will be to bring all of said wheels into register with each other as regards the figures. Said wheels can thus be turned back so that all the zeros thereon appear at the slot in the 30 casing 78. The knob 147 is then moved to the right, which withdraws the teeth 142 into the slotted tube, leaving the wheels free to rotate, and the knob 150 is turned back to its normal position.

35 *Error correction.*—It is desirable to provide means for correcting an error made by inadvertently striking the wrong numeral key of the typewriting machine. Should the operator, in order to correct an error made 40 by depressing the wrong key, move the carriage back two spaces, to bring the printed numeral one letter-space to the right of its original position, the same movement will bring the computing wheel which has just 45 been operated one space to the right of, and out of engagement with the teeth of the computing shaft. On the left hand end of the tube 71 which surrounds the right-half of the computing shaft 35 is formed a correcting tooth 153, (Figs. 24, 26) the normal 50 position of which will be in line with one of the recesses 73 of the internal gear teeth of the computing wheels 72, so that, by the said movement of two spaces to the right, 55 said tooth is caused to engage such a recess. Thereby said computing wheel can be turned back to any desired position, preferably the original position before the wrong numeral key was struck. Suppose, for instance, 60 the operator intended to strike the numeral key "6," but by inadvertence struck the numeral key "7," then it would be desirable to turn back the computing wheel 72 seven-tenths of a revolution, and then 65 move the computing carriage 79 one space

leftward. This operation could be performed either before or after the operator erases the wrongly written numeral. After these operations have been performed, the computing mechanism has been brought 70 back to the same condition as before the error. Since this operation can only take place if the computing wheel acted upon is unlocked, provision must be made for unlocking the same before the correction is 75 made. For this purpose the knob 150 (Fig. 29) is turned until the wide part of the eccentric on shaft 149 (Fig. 14) swings the arm 151 of the locking lever 112 forwardly and thereby moves said locking lever out of 80 engagement with the computing wheel 72, permitting said computing wheel and associated figure wheel 77 to turn with the tooth 153 on the sleeve 71. Fast on the right-hand end of said sleeve is a pinion 154 (Figs. 26 and 31) which meshes with a pinion 156 fast on a shaft 157. Loosely mounted on the shaft 157 is a knob 158 the left-hand end of which has ten notches 159 formed therein, adapted to engage pins 160 fast on the shaft 157, and has the "0" to "9" marked on its periphery, one of the numerals opposite each notch. After the computing wheel 72 has been unlocked to correct an error, the knob 158 is turned until the same number 90 thereon as had been erroneously written is brought opposite the bent upper end of a depressor rod 167. The knob 158 is then moved leftward along the shaft 157 until the notches 159 engage the pins 160. When the 95 knob 158 is turned back to zero, the same angular motion is transmitted to the figure wheel 77, thus restoring said wheel to its previous position. The knob 158 carries a pin 166 (Figs. 26, 29) which, as the knob is 100 turned back to zero, engages the bent upper end of the depressor rod 167 connected to a lever 169 engaging an arm 171 extending from the latch 136, which was engaged by a pin extruded from the controller upon the 105 operation of a numeral key, which latch 136 is now, however, engaged by said lever 169 at a corresponding point in the revolution of the correcting knob 158, that is, one half of one-tenth of a revolution before the completion of the turn. The effect of this is to release the arm 134, and withdraw the releasing finger 119, and so cause the locking lever 112 to again lock the computing wheel 110 upon the ordinary depression of a numeral key. When an error is made in subtraction, the figure wheel 77 may be returned to its original position by setting the computing mechanism to addition, and then moving the carriages 82 and 79 back one letter-space, 115 and depressing the same numeral key as had been erroneously depressed.

An error is corrected by the use of the correction mechanism, in the following manner: Assuming that the operator by 120

mistake has written and added "7" instead of "2". The carriage is now in such position that the tooth or master-wheel 70 engages the wheel of next lower denomination 5 to that on which the error was made. The paper carriage is therefore retracted one step, to bring the erroneously driven wheel into register with the master-wheel 70 and the lock-releaser 119, Figs. 14, 15. The 10 knob 158 is then rotated until "7" thereon shows at the index (Fig. 29), and then the knob is thrust to the left from the position at Fig. 26 to the position at Fig. 28, with the spurs 160 (on shaft 157) engaging the 15 internal gear 159 with which said knob 158 is provided (Fig. 27). By reason of such endwise thrust of the knob 158, the arm 162 (Fig. 4) is cammed down, rocking shaft 163 (Fig. 29), depressing arm 164 on said shaft. 20 This arm engages pin 165, Fig. 4, and thrusts down link 129, rocking down the arm 128 (Fig. 29), which, by engagement with the trip arm 126 pivoted on arm 125, rocks down said arm 125, rotating the shaft 25 122, and swinging the arm 119 thereon forwardly into engagement with the releasing arm 123 of the locking dog 112 belonging to the computing wheel at the moment in engagement with the master wheel. This releases 30 said computing wheel, so that it can be rotated. Next, the carriage is set back an additional letter-space, to bring the released computing wheel into engagement with the correcting pin 153, Fig. 26. During this 35 last movement of the carriage, the releasing arm 119 swivels upon its vertical pivot on the collar 121, to accommodate the lateral movement of the arm 123 and locking dog 112; said releasing arm 119 being notched 40 (Fig. 15) to have a locking engagement with said arm 123 for this purpose. (Said releasing arm 119 may swivel to either right or left, one of such movements being illustrated in dotted lines at Fig. 15). The 45 erroneous computation wheel being now released from its dog and also in engagement with the correction pin 153, Fig. 26, the knob 158 is rotated seven points, until the figure "0" thereon shows at the index; this 50 rotation being in subtraction direction or counterclockwise at Fig. 29. Or, looking at Fig. 31, it will be seen that the rotation of the knob-shaft 157 is in clockwise direction at this time. This movement is communicated 55 through pinion 155 to gear 154, which also moves in clockwise direction at Fig. 31, viz., in direction for subtraction; said gear 154 being fixed to hollow shaft 71, carrying the correction-pin 153, which moves the engaged computation wheel 72 backwardly seven points. The knob 158 may then be 60 returned along shaft 157 to normal Fig. 26 position, this movement being accompanied by a release of cam arm 162, whereby the

dog-releasing arm 119 is permitted to be returned to normal position by spring 135, Fig. 29, so that the computation wheel just rotated may be re-locked by its dog 112. The numeral type key "2" may now be struck, the erroneous number "7" on the work-sheet having first been erased. Thus the error may be corrected while the machine still remains in condition for addition. Whether the number erroneously written is larger or smaller than the correct number, 65 the process of correction may be the same, first to rotate the computation wheel backwardly to cancel the number computed, and then to insert the correct number in the wheel by the operation described. In this 70 manner correction may proceed along as many wheels as necessary, by correcting the wheels one at a time. It is also apparent that the position of a number wheel may be altered by rotating the same by the knob 75 158, whether a new number is thereupon inserted in said wheel or not. Whenever the machine is set for subtraction, the direction of rotation of the correcting knob 158 must be the reverse of that just described, in correcting an error. For instance, if "4" has 80 been subtracted instead of "3", the knob 158 must be turned in a direction to add "4" in the number wheel; and thereupon the key for "3" may be struck, to subtract that 85 amount. Thus provision is made for correcting such errors, whether the machine is set for addition or subtraction. If the correction involves several number wheels, when adding, the operator may resort to the 90 expedient of setting the machine for subtraction, to subtract out the numbers on the various wheels, and may then restore the machine to condition for addition, and proceed to add the correct numbers. A contrary course may be pursued if the machine is subtracting when an error is made involving 95 several wheels.

Driving mechanism.—The motive power is here shown as derived from a spring which 100 may be wound up either automatically by a reciprocating motion of the typewriter carriage or voluntarily, by a crank, at suitable intervals. I will describe only the modification in which the spring is wound up 105 automatically, it being then unnecessary to describe the mechanism for winding by hand.

The usual spring 175 (Fig. 30) for advancing the typewriter carriage is now 110 placed at the right of the machine, and a band 176 (Figs. 1, 29) connected to the casing 177 of said spring is passed around an idle wheel 178 (Fig. 1) and thence to the typewriter carriage. Said casing 177 carries 115 a pawl 179 which engages a tooth of a wheel 180 loose on a fixed shaft 181, and thereby, when the carriage is retracted to begin a

new line on the machine, said casing is rotated and imparts rotation to the wheel 180.

Said wheel 180 has formed thereon a gear 5 wheel 182 which engages a pinion 183 loose on a shaft 184, and connected by a sleeve 185 with a casing 186 secured to the outer end of the spring 187, the inner end of said spring being attached to the shaft 184. Said 10 casing 186 has formed thereon a gear wheel 188 which meshes with a pinion 189 connected by a ratchet clutch 190 with the shaft 49 to permit the carriage 82 to be run back and forth even though no computing is done. 15 The spring 187 thus continually furnishes power to rotate the shaft 49 and is itself wound up by means of the casing or drum 177. In this way force is constantly applied to drive the computing shaft.

20 *Subtracting.*—The attachment may also be used for subtracting. For this purpose the bevel gear 40 is moved away from the bevel gear 39, and a bevel gear 201, (Fig. 36) opposite to the gear 40, is secured on the 25 shaft 41 so as to mesh with the gear 39. The shaft 35 will now be driven in the reverse direction, which will effect the operation of subtracting. Instead of the means shown for shifting and securing these gears, any 30 common shifter can be used, an example of which is seen in the patent to Kaussen, No. 747,977, in which the shifter 211 may be shifted along the drive-shaft 41, to connect either pinion 40 or pinion 201 thereto; the 35 shifter being operated by the usual handle 212.

I claim:—

1. In a computing device, the combination, 40 with key levers, of a transmitter carrier, movable devices supported by said carrier, a rotary controller having slideways, bolts slidable therein and adapted to be brought opposite to said devices, computing mechanism, means for controlling said computing 45 mechanism by the rotary movement of the controller, said devices being adapted, when selectively moved by the operation of a numeral key, to protrude one end of the corresponding bolt beyond said controller, and 50 resetting means adapted to engage said protruded end of the bolt, and return the bolt to its normal position, said bolt being of such magnitude relative to the controller, that its other end protrudes from the slide-way 55 of said bolt in such normal position, substantially as described.

2. In a computing device, the combination, 60 with key levers, of a transmitter carrier, movable devices supported by said carrier, a rotary controller, bolts slidable therein, and adapted to be brought opposite to said devices, computing mechanism, means for controlling said computing mechanism by the rotary movement of the controller, said de-

vices being adapted, when selectively moved 65 by the operation of a numeral key, to protrude one end of the corresponding bolt beyond said controller, and means, independent of the operation of the numeral key, for automatically withdrawing said device 70 instantaneously after so protruding said bolt, substantially as described.

3. In an apparatus of the character described, the combination of computing mechanism, a rotary controller therefor, 75 bolts carried by said controller and movable relatively thereto, a stop for said bolts, and means for selectively protruding a bolt into a position to be arrested by said stop upon the rotary movement of the controller, said 80 means, when protruding the bolt, being located outside of said controller, substantially as described.

4. In an apparatus of the character described, the combination of computing 85 mechanism, a rotary controller therefor, bolts carried by said controller and movable relatively thereto, a stop for said bolts, devices for selectively protruding a bolt into a position to be arrested by said stop upon 90 the rotary movement of the controller, means for selectively operating said devices upon the downward movement of a numeral key, and means for returning said devices to their normal position during said downward movement, substantially as described. 95

5. In an apparatus of the character described, the combination of numeral keys, computing mechanism, a rotary controller therefor, bolts slidable in said controller, 100 spring-resisted devices adapted to engage said bolts to protrude them from the controller, and levers, operated upon the depression of a numeral key, and engaging said devices during part only of the forward 105 movements of said levers, to cause said devices to abut against said bolts, said levers being free to return past said devices on the return movement of the levers, substantially 110 as described.

6. In a computing attachment for typewriters, the combination of key levers, wires adapted to be operatively connected with the key levers, bell crank levers connected with the other ends of the respective wires, 115 a transmitter carrier, rods slidably supported therein, adapted to be moved in said carrier by the other arms of said levers, springs for returning said rods to their normal position, a rotary controller, bolts sliding therein and adapted to be brought opposite to the rods in the transmitter carrier, bell crank levers pivoted on said controller, 120 said levers being adapted to be moved by the transmitter rods and also adapted to move the controller bolts, a spring around the outer arms of all the levers, computing mechanism, and means for controlling said 125

computing mechanism by the rotary movement of the controller, substantially as described.

7. In a computing attachment for typewriters, the combination of key levers, wires adapted to be operatively connected with the key levers, bell crank levers connected with the other ends of the respective wires, a transmitter carrier, rods slidably supported therein, adapted to be moved in said carrier by the other arms of said levers, springs for returning said rods to their normal position, the ends of said rods being movable laterally to permit the bell crank levers to return, a rotary controller, bolts slidable therein and adapted to be brought opposite to the rods in the transmitter carrier, bell crank levers pivoted on said controller, said levers being adapted to move the controller bolts, a spring around the outer arms of all the levers, computing mechanism, and means for controlling said computing mechanism by the rotary movement of the controller, substantially as described.

8. In a computing attachment for typewriters, the combination of key levers, wires adapted to be operatively connected with the key levers, bell crank levers connected with the other ends of the respective wires, a transmitter carrier, rods slidably supported therein, adapted to be moved in said carrier by the other arms of said levers, springs for returning said rods to their normal position, said rods being movable laterally to permit the bell crank levers to return, a rotary controller, bolts slidable therein and adapted to be brought opposite to the rods in the transmitter carrier, bell crank levers pivoted on said controller, said levers being adapted to be moved by the transmitter rods and also adapted to move the controller bolts, a spring around the outer arms of all the levers, said controller being formed with a circumferential groove and the bolts being formed with recesses to receive the arms of the bell crank levers passing through said grooves, computing mechanism, and means for controlling said computing mechanism by the rotary movement of the controller, substantially as described.

9. In an apparatus of the character described, the combination of numeral keys, computing mechanism, a rotary controller therefor, operating mechanism therefor, an arresting device for arresting said controller, means for providing rotational pressure to withdraw said arresting device, an escapement mechanism for preventing its withdrawal, and means whereby said escapement mechanism may be actuated with the operation of a numeral key to release the means for withdrawing said arresting device, substantially as described.

10. In an apparatus of the character described, the combination of computing mechanism, a controller therefor, a rotary stop for arresting said controller, means for rotating said stop, escapement mechanism for preventing its rotation, and means actuated with the operation of a numeral key for actuating said escapement mechanism to first release and then arrest said stop, substantially as described. 75

11. In an apparatus of the character described, the combination of numeral keys, computing mechanism, a controller therefor, a rotary stop for arresting said controller, means for rotating said stop, and an escapement comprising a device rotating with said stop, a rock shaft adapted to be rocked with the operation of a numeral key, and parts carried by said rock shaft offset from each other, and adapted to successively engage said device in different angular positions of the rock shaft to arrest the device, substantially as described. 80 85

12. In an apparatus of the character described, the combination of numeral keys, computing mechanism, a controller therefor, a stop for arresting said controller, means for providing pressure to withdraw said stop, an escapement operatively connected with said stop, and a device arranged to be operated by a numeral key and having parts respectively adapted in different positions of said device to successively arrest said escapement, substantially as described. 90 95

13. In an apparatus of the character described, the combination of numeral keys, computing mechanism, a controller therefor, means for arresting said controller, an escapement for releasing said arresting means, and an operative connection between said escapement and a numeral key, whereby, in the downward movement of a numeral key, the escapement is permitted to move a part only of its complete releasing movement, and to complete said releasing movement 100 105 110 upon the return movement of the numeral key, substantially as described.

14. In an apparatus of the character described, the combination of numeral keys, computing mechanism, a rotary controller therefor, means independent of the operation of the numeral keys for rotating said controller, a rotary device adapted to first release and then arrest the controller, and means controlled by the operation of a numeral key for first releasing and then arresting said device, substantially as described. 115 120

15. In a computing attachment for typewriters, the combination of numeral keys, a computing shaft, driving mechanism therefor, and means for releasing said shaft to permit it to be rotated by the driving mechanism, comprising a universal bar, means whereby said bar is shifted by the operation 125 130

of any one of the numeral keys of the typewriter, a shaft operatively connected with said computing shaft, a lug carried thereby, and an escapement connected with the universal bar and having thereon a device with openings therethrough offset from each other to permit the passage of said lug therethrough, substantially as described.

16. In a computing attachment for typewriters, the combination of numeral keys, a rotary controller, bolts carried thereby, means operated by the depression of a numeral key for extruding selectively one of said bolts, means engaging the bolt previously extruded to prevent the rotation of said controller, means for rotating said controller when the previously extruded bolt is released, controlled by the movement of the typewriter key for releasing the latter bolt, a wedge engaging the end of the last named bolt to return it to its normal position, and computing mechanism variably controlled by the rotation of said controller, substantially as described.

25 17. In a typewriting and computing machine, having devices arranged to print at a common point, the combination of numeral keys, a paper carriage, a computing carriage, means whereby the computing carriage is moved with the paper carriage and in the same direction one typewriting space at a time by the operation of a numeral key, computing devices movable with said computing carriage, a shaft passing through said computing devices, a suitable support for said shaft, and means for imparting a variable rotation to said shaft dependently upon the operation of a numeral key, said shaft being provided with means, located substantially opposite to the common printing point of the machine, for successively engaging said computing devices to impart rotary motion thereto, substantially as described.

45 18. In a typewriting and computing machine, the combination of numeral keys, a paper carriage, a computing carriage, means whereby the computing carriage is moved with the paper carriage and in the same direction one typewriting space at a time by the operation of a numeral key, computing devices movable with said computing carriage, a shaft passing through said computing devices, a suitable support for said shaft, and means for imparting a variable rotation to said shaft dependently upon the operation of a numeral key, said shaft being provided with means for successively engaging said computing devices to impart rotary motion thereto, substantially as described.

60 19. In a typewriting and computing machine, the combination of numeral keys, a paper carriage, a computing carriage, means whereby the computing carriage is moved with the paper carriage and in the same

direction one typewriting space at a time by the operation of a key, computing devices movable with said computing carriage, a shaft passing through said computing devices, a suitable support for said shaft, means for imparting a variable rotation to said shaft dependently upon the operation of a numeral key, said shaft being provided with means for successively engaging said computing devices to impart rotation thereto, and tubes within the computing devices and surrounding said shaft except at said means, and secured independently of the shaft, substantially as described.

70 20. In a typewriting and computing machine, the combination of numeral keys, a paper carriage, a computing carriage, means whereby the computing carriage is moved with the paper carriage and in the same direction one typewriting space at a time by the operation of a key, computing devices movable with said computing carriage, a shaft passing through said computing devices, a suitable support for said shaft, means for imparting a variable rotation to said shaft dependently upon the operation of a numeral key, said shaft being provided with means for successively engaging said computing devices to impart rotation thereto, and a fixed tubular means around said shaft and within the computing devices to separate said computing devices therefrom, substantially as described.

80 21. In a computing device, the combination of a series of computing wheels, numeral keys to operate them *seriatim*, means actuated by the arrival of each computing wheel at a pre-determined point in its rotation for advancing the next computing wheel one-tenth of a revolution, and an assisting mechanism to operate said means for effecting said advance, said assisting mechanism effective at the numeral key operation.

90 22. In a computing device, the combination of a series of computing wheels, numeral keys to operate them *seriatim*, a series of transfer wheels adapted to "carry" from one wheel to the next of a higher denomination, and an assisting mechanism effective at the numeral key operation and rotated independently of the rotary movement of the computing mechanism, and arranged to engage a transfer wheel when the latter has been brought to a predetermined point by the rotary movement of a computing wheel, and assist the turning of said transfer wheel.

100 23. In a computing device, the combination of a series of computing wheels, a series of transfer wheels to "carry" from one wheel to the next of a higher denomination, and an assisting mechanism actuated by the movement of a denomination-controlling computing carriage and rotated independently of the rotary movement of the computing mechanism, and arranged to engage

130

a transfer wheel when the latter has been brought to a predetermined point by the rotary movement of a computing wheel, and assist the turning of said transfer wheel.

5 24. In a computing device, the combination of a series of computing wheels, numeral keys to operate them *seriatim*, a series of transfer wheels to "carry" from one wheel to the next of a higher denomination, 10 and an assisting shaft having teeth thereon adapted when the transfer wheel has been brought to a predetermined position to engage the teeth of said transfer wheel and assist them in turning, said assisting shaft 15 effective at the operation of any numeral key.

25. In a computing device, the combination of a series of computing wheels, transfer wheels adapted to "carry" from one 20 wheel to the next of a higher denomination, an assisting shaft having teeth thereon adapted when the transfer wheel has been brought to a pre-determined position to engage the teeth of said transfer wheel and 25 assist them in turning, and means actuated by the movement of the computing carriage in either direction for rotating said assisting shaft in the same direction and rotated independently of the rotary movement of 30 the computing mechanism, substantially as described.

26. In a computing device, the combination of a series of computing wheels, a series of transferring wheels for "carrying" 35 from one computing wheel to the next of a higher denomination, an assisting shaft having a part adapted to engage said transfer wheels when moved into a pre-determined position to assist their rotation, a 40 longitudinal rack, a gear wheel, rotatably attached to the carriage and meshing with said rack, and an operative connection between said gear wheel and the shaft, whereby the shaft is rotated by the rotation of 45 the gear wheel when the carriage is moving in one direction but is disengaged therefrom when the carriage is moving in the opposite direction, substantially as described.

50 27. In a computing device, the combination of a series of computing wheels, a series of transferring wheels for "carrying" from one computing wheel to the next of a higher denomination, an assisting shaft having a 55 part adapted to engage said transfer wheels when moved into a pre-determined position to assist their rotation, a longitudinal rack, a gear wheel at each end of the carriage meshing with said rack, and a connection between each gear wheel and the corresponding end of the assisting shaft, alternately operative when the carriage is moving in one direction and inoperative when it is moving in the opposite direction, substantially 60 as described.

65

28. In a computing device, the combination of a series of computing wheels, a series of transfer wheels for "carrying" from one computing wheel to the next of a higher denomination, an assisting shaft having a part 70 adapted to engage a transfer wheel when moved in a pre-determined position to assist its rotation, a carriage for said computing wheels and transfer wheels, and means operated at the movement of the carriage for 75 actuating said shaft.

29. In an apparatus of the character described, the combination of a series of computing wheels, a tube therethrough having a longitudinal series of apertures, and a device in said tube movable longitudinally therein, said device and bar having, the one an oblique slot and the other a pin engaging said slot, to project said teeth upon the longitudinal movement of said device, sub- 80 stantially as described.

30. In an apparatus of the character described, the combination of an apertured tube, a series of wheels thereon, a bar in said tube having a part adapted to project 90 through said aperture, means for preventing the longitudinal movement of the bar, a device in said tube adapted to move longitudinally therein, said device and bar having, the one an oblique slot and the other a pin 95 engaging said slot, whereby, on the longitudinal movement of said device, said part is projected from said tube, substantially as described.

31. In an apparatus of the character de- 100 scribed, the combination of a tube having a series of apertures, wheels thereon, one over each aperture, a bar in said tube having oblique slots, and teeth, one adapted to project through each aperture, a rod on each side of 105 said bar, pins connecting said rods through said slots, and a knob at the end of said tube to which said rods are connected, substantially as described.

32. In an apparatus of the character de- 110 scribed, the combination of a series of wheels, a support therefor passing axially through said wheels, a device adapted to move transversely relative to said support and having parts rigid therewith and adapted to engage 115 the respective wheels when so moved transversely, a device movable longitudinally of said support, and connections between the two devices whereby from the longitudinal movement of the one is produced a transverse movement to the other, substantially as described.

33. In apparatus of the character de- 120 scribed, the combination of a series of apertured computing wheels, a shaft passing 125 through said wheels, a tube surrounding said shaft and having a laterally projecting tooth thereon, and means for turning said tube to turn any desired computing wheel.

34. In an apparatus of the character de- 130

- scribed, the combination of a rotary shaft, a series of wheels thereon, said shaft having a tooth adapted to engage said wheels in succession when brought into the proper position, a tube around said shaft and having a tooth at its end adjacent to the tooth on the shaft, and means for turning said tube to turn a wheel on said latter end, comprising a gear-wheel on the other end of the tube, a shaft having a gear wheel meshing with the first gear wheel, and having a pin, and a knob slideable on said latter shaft and having a series of recesses adapted to engage said pin, said knob being suitably numbered to indicate the amount to which it should be turned, substantially as described.
35. In an apparatus of the character described, the combination of a rotary shaft, a series of wheels thereon, said shaft having a tooth adapted to engage said wheels in succession when brought into the proper position, a tube around said shaft and having a tooth at its end adjacent to the tooth on the shaft, and means for turning said tube, to turn a wheel on said latter end, comprising a gear-wheel on the other end of the tube, a shaft having a gear-wheel meshing with the first gear-wheel, and having a pin, a knob slideable on said latter shaft and having a series of recesses adapted to engage said pin, said knob being suitably numbered to indicate the amount to which it should be turned, means for locking the wheel over said tube end, and means actuated by the sliding of the knob for releasing said locking means, substantially as described.
36. In a computing attachment for typewriters, the combination of a computing carriage, a series of computing devices therein, and partitions fixed in the computing carriage between said devices, said devices being arranged in groups of three, each group and a partition adjacent thereto being of a total width equal to four of the said uniform spaces, and means for transferring from a computing device adjacent to said partition on the other side.
37. In a computing attachment for typewriters, the combination with computing devices, of a frame for inclosing said devices, said devices being arranged in said frame in groups of three, and partitions secured to the frame and extending transversely thereof and occupying the spaces between adjacent groups, the computing devices comprising means for displaying figures, the frame being provided with means for concealing all the figures except one row thereof, and the partitions being formed with division marks in line with the row of figures so displayed.
38. The combination with a typewriting machine having a paper carriage and type keys, of a series of computing devices, operating mechanism therefor, and means for variably controlling said operating mecha-

nism by the depression of the numeral keys, said computing devices being provided with means for visibly spacing the same into groups of three, the distance from a device of one group to the corresponding device of the next adjacent group being equal to four such spaces, said series containing a sufficient number of such groups to form a plurality of commercial totalizers, and to permit substantial variations in position of said totalizers, and means extending uninterruptedly along the entire series of devices for "carrying" from any device to the next adjacent on the left, substantially as described.

39. In a combined typewriting and computing machine, the combination with type-operating numeral keys and a typewriter carriage, of a computing mechanism including, as primary elements, a computing head and a master wheel, one of said primary elements connected to said carriage for a step-by-step movement relative to the other of said primary elements, and means to enable the keys to control the rotation of the master wheel, said computing head including a series of computing wheels all operable by said master wheel, said computing wheels being sufficient in number to enable several computations each in hundreds of millions to be performed concomitantly, said series of computing wheels being divided into groups of three, each group spaced from the next by a letter-space interval to permit locating columns at any desired positions across the work sheet.

40. In a combined typewriting and computing machine, the combination with type-operating numeral keys and a typewriting carriage, of a computing mechanism including, as primary elements, a computing head and a master wheel, one of said primary elements connected to said carriage for a step-by-step movement relative to the other of said primary elements, and means to enable the keys to control the rotation of the master wheel, said computing head including a series of computing wheels all operable by said master wheel, said computing wheels being sufficient in number to enable several computations each in hundred of millions to be performed concomitantly, said series of computing wheels being divided into groups of three, each group spaced from the next by a letter-space interval to permit locating columns at any desired positions across the work sheet, and a train of tens-carrying connections extending uninterruptedly throughout the entire series of computing wheels.

41. In a combined typewriting and computing machine, the combination with a typewriting carriage and a set of typewriting numeral keys, of a computing mechanism including, as primary elements, a multiple-length computing head and a master wheel; one of said primary elements con-

nected to said carriage for a step-by-step movement relatively to the other of said primary elements; and means to enable the keys to control the rotation of the master wheel;

5 said computing head including an extended series of computing wheels all operable by said master wheel, all of said computing wheels being divided into groups of three, each group spaced from the next by a letter-space interval to permit grouping of the 10 column at any desired positions across the work sheet.

42. In a combined typewriting and computing machine, the combination with a typewriting carriage and a set of typewriting numeral keys, of a computing mechanism including, as primary elements, a multiple-length computing head and a master wheel; one of said primary elements connected to said carriage for a step-by-step movement relatively to the other of said primary elements; means to enable the keys to control the rotation of the master wheel; said computing head including an extended series of computing wheels all operable by said master wheel, all of said computing wheels being divided into groups of three, each group spaced from the next by a letter-space interval to permit grouping of the 20 columns at any desired positions across the work sheet, and a train of tens-carrying connections extending uninterruptedly throughout the entire series of computing wheels.

43. In a typewriting and computing machine the combination of numeral keys, connections extending therefrom and constructed to actuate computing devices, a releasing bar or device controlling said connections, a key connected to said bar to move it to disconnect the numeral keys, and a separate key to move said bar to re-connect the numeral keys to the adding devices.

44. In a typewriting and computing machine the combination of numeral keys, connections extending therefrom and constructed to actuate computing devices, a releasing bar or device controlling said connections, a key connected to said bar to move it to disconnect the numeral keys, and a separate key to move said bar to re-connect the numeral keys to the adding devices, said connecting and disconnecting keys being mounted upon the ends of a lever which is connected to said bar.

45. In a computing machine, the combination with a set of computing devices, a power-driven indexing wheel having independently settable escapement teeth, and a dog device to coöperate with said teeth, of a series of numeral keys, and a series of jacks operated by said keys and effective to set said escapement teeth.

46. In a computing machine, the combination with a set of computing devices, a power-driven indexing wheel having inde-

pendently settable escapement teeth, and a dog device to coöperate with said teeth, of a series of numeral keys, and a series of jacks operated by said keys and effective to set said escapement teeth; automatically releasable connections being provided between said keys and said escapement teeth. 70

47. In a computing machine, the combination with a set of computing devices, a power-driven indexing wheel having independently settable escapement teeth, and a dog device to coöperate with said teeth, of a series of numeral keys, and a series of jacks operated by said keys and effective to set said escapement teeth; said jacks in the form 75 of trips, and means being provided for automatically releasing the jacks from the keys.

48. In a computing machine, the combination with a set of computing devices, a power-driven indexing wheel having independently settable escapement teeth, and a dog device to coöperate with said teeth, of a series of numeral keys, and a series of jacks operated by said keys and effective to set 80 said escapement teeth; automatically releasable connections being provided between said keys and said escapement teeth; said connections including levers operated by the keys and trips operated by said levers, and springs to return the jacks to normal positions in advance of the return of the keys 85 to normal positions.

49. In a computing machine, the combination with a set of computing devices, a power-driven indexing wheel having independently settable escapement teeth, and a dog device to coöperate with said teeth, of a series of numeral keys, and a series of jacks operated by said keys and effective to set 90 said escapement teeth; automatically releasable connections being provided between said keys and said escapement teeth; said connections including levers operated by the keys and trips operated by said levers, and springs to return the jacks to normal positions in advance of the return of the keys 95 to normal positions, said jacks arranged in a circle, and said levers having a corresponding arrangement.

50. An escapement device for a computing mechanism comprising, in combination, an indexing wheel, a series of settable teeth mounted at intervals around the wheel, a helical spring ring surrounding the wheel, and means to enable said spring to hold said 100 teeth in normal position.

51. An escapement device for a computing mechanism comprising, in combination, an indexing wheel, a series of settable teeth mounted at intervals around the wheel, a set 105 of detents pivoted upon said wheel, recesses provided in said teeth and engaged by said detents, and a helical spring ring surrounding all of said detents.

52. The combination with keys, of a power- 115

driven indexing wheel and a set of computing wheels controlled thereby, a set of movable teeth mounted at intervals upon said indexing wheel, an escapement device to cooperate with said teeth, means to enable said keys to set said teeth and operate said escapement device, and means to retract said escapement teeth.

53. The combination with a power-driven indexing wheel, a set of computing wheels controlled thereby, and a set of keys, of a set of movable teeth mounted at intervals upon said indexing wheel, means to enable said keys to set said teeth, a pinion engageable by said teeth, a secondary escapement wheel connected to said pinion, a universal bar or device operated by said keys, and a dog or feed device operated by said universal bar and coöperating with said secondary escapement wheel.

54. The combination with a power-driven indexing wheel, a set of computing wheels controlled thereby, and a set of keys, of a set of movable teeth mounted at intervals upon said indexing wheel, means to enable said keys to set said teeth, a pinion engageable by said teeth, a secondary escapement wheel connected to said pinion, a universal bar or device operated by said keys, and a dog or feed device operated by said universal bar and coöperating with said secondary escapement wheel; said secondary escapement wheel being of substantially larger diameter than said pinion.

55. In a combined typewriting and computing machine having a keyboard including a set of numeral keys, the combination of a set of bell-crank mounted back of the keyboard, a set of links connecting the numeral keys to the bell-crank, links extending from said bell-crank to one side of the machine, a power-driven indexing wheel mounted near the ends of said links at the side of the machine, levers connected to the ends of said links and mounted in proximity to said indexing wheel, a series of settable teeth on said indexing wheel, means to enable said levers to set said teeth, means controlled by said keys for permitting said indexing wheel to feed, and a set of computing wheels controlled by said indexing wheel.

56. The combination of a series of numeral keys, power-driven computing devices, an indexing wheel connected to said computing devices to control their movements, teeth independently settable upon said indexing wheel, means for setting said teeth, a pinion rotatable by means of said teeth, and a step-by-step escapement mechanism for said pinion controlled by said keys.

57. The combination of a series of numeral keys, power-driven computing devices, an indexing wheel connected to said computing devices to control their movements, teeth independently settable upon said in-

dexing wheel, a circular series of independently operable devices operated by said keys, for setting said teeth, a pinion rotatable by means of said teeth, a step-by-step escapement mechanism for said pinion controlled by said keys, and means for returning each tooth from projected to normal position after it has turned said pinion.

58. The combination of a series of numeral keys, power-driven computing devices, an indexing wheel connected to said computing devices to control their movements, teeth independently settable upon said indexing wheel, a circular series of independently operable devices operated by said keys, for setting said teeth, a pinion rotatable by means of said teeth, a step-by-step escapement mechanism for said pinion controlled by said keys, and means for returning each tooth from projected to normal position after it has turned said pinion; means being provided to detain said teeth in normal positions.

59. The combination of a series of numeral keys, power-driven computing devices, an indexing wheel connected to said computing devices to control their movements, teeth independently settable upon said indexing wheel, means for setting said teeth, a pinion rotatable by means of said teeth, a step-by-step escapement mechanism comprising a secondary escapement wheel connected to said pinion, and a pair of vibrating escapement teeth connected to a universal bar which is reciprocated by said keys.

60. The combination with power-driven computing wheels, of an indexing wheel connected thereto and having movable teeth, key-controlled devices upon one side of said indexing wheel to cause said teeth to project from the opposite side of the indexing wheel, and step-by-step controlling mechanism engaging the projected teeth to permit variable rotation of said indexing wheel.

61. The combination with power-driven computing wheels, of an indexing wheel connected thereto and having movable teeth, devices to set said teeth, keys for operating said setting devices, step-by-step escapement or feed mechanism engaging the projected teeth to permit variable rotation of said indexing wheel, and means for providing for the return of the setting means in the advance of the return of the keys, so as to clear said indexing wheel and the devices thereon to permit free rotation of the wheel.

62. The combination of power-driven computing wheels, a rotary set of teeth connected to said computing wheels to control their movements, means controlled by a set of numeral keys for setting any selected tooth into effective position, a rotary device to engage the projected tooth to prevent rotation of the set of teeth, and a key-controlled escapement mechanism connected

to the rotary device to permit step-by-step rotation of said rotary device by means of the projected teeth.

63. The combination of power-driven computing wheels, a rotary set of teeth connected to said computing wheels to control their movements, means controlled by a set of numeral keys for setting any selected tooth into effective position, a rotary device to engage the projected tooth to prevent rotation of the set of teeth, and a key-controlled escapement mechanism connected to the rotary device to permit step-by-step rotation of said rotary device by means of the projected teeth; means being provided for restoring each tooth to ineffective position after passing said rotary device.

64. The combination with power-driven computing wheels, of a rotary set of teeth connected to said computing wheels to control the same, a stationary set of key-controlled tooth-setting devices, and a step-by-step key-controlled escapement mechanism to coöperate successively with the projected teeth.

65. The combination with power-driven computing wheels, of a rotary set of teeth connected to said computing wheels to control the same, a stationary set of key-controlled tooth-setting devices, and a step-by-step key-controlled escapement mechanism to coöperate successively with the projected teeth; means being provided to restore each tooth to normal ineffective position after passing said escapement mechanism.

66. The combination with power-driven computing wheels, of a rotary set of teeth connected to said computing wheels to control the same, a stationary set of key-controlled tooth-setting devices, a step-by-step key-controlled escapement mechanism to coöperate successively with the projected teeth; means being provided to restore each tooth to normal ineffective position after passing said escapement mechanism, and means to detain the tooth in normal position.

67. The combination with power-driven computing wheels, of a rotary set of teeth connected to said computing wheels to control the same, a stationary set of key-controlled tooth-setting devices, and a step-by-step key-controlled escapement mechanism to coöperate successively with the projected teeth; means being provided for permitting the return of each setting device to normal position in advance of its operating key, to clear the rotary set of escapement teeth.

68. The combination with a series of computing wheels and numeral keys for effecting the operation of said wheels *seriatim*, of a tens-carrying mechanism including an auxiliary power-actuated device coöoperative with any of said wheels at the operation of any numeral key, to turn the wheel of next higher denomination.

69. The combination with a series of com-

puting wheels, numeral keys, and means co-operating with said keys to effect the operation of said wheel *seriatim* as the keys are operated, of means for carrying tens from one wheel to the next, comprising an interponent called into action by a wheel of low denomination and having means to actuate a wheel of higher denomination, and an auxiliary prime-moving device capable of acting at the operation of any numeral key, to act upon said interponent to cause it to move the wheel of higher denomination.

70. The combination with a series of computing wheels, of means for carrying tens from one wheel to the next, comprising an interponent called into action by a wheel of low denomination and having means to actuate a wheel of higher denomination, and an auxiliary prime-moving device to act upon said interponent to cause it to move the wheel of higher denomination; said auxiliary device being connected to a power-driven carriage forming part of the computing mechanism, to be driven by said carriage.

71. The combination with a series of computing wheels, of means for carrying tens from one wheel to the next, comprising an interponent called into action by a wheel of low denomination and having means to actuate a wheel of higher denomination, and an auxiliary prime-moving device to act upon said interponent to cause it to move the wheel of higher denomination; said auxiliary device extending along the series of wheels and mounted for rotation and constructed to act upon any of a series of interponents for the purpose specified.

72. The combination of a series of computing wheels having internal teeth, a shaft extending through the wheels and having a tooth to engage the wheels, means for effecting relative movement between said tooth and wheels in the direction of the axis of the shaft, a tube inclosing the shaft, a tooth upon said tube, in proximity to the tooth on said shaft, and means for rotating said tube at will to correct an error in the setting of any wheel.

73. In combination, a series of computing dial wheels divided into groups of three, a frame concealing all of the figures or the wheels except one row, and partitions between the groups, formed with division marks in line with the exposed row of figures.

74. The combination with a totalizer comprising a set of wheels, of a set of numeral keys, means to coöperate with said keys to turn the wheels of the totalizer *seriatim* as the keys are operated, manually shiftable means to set said totalizer to either add or subtract at the operation of the keys, and manually operable means operable while the totalizer remains set for either addition or subtraction, for making a correction on any

wheel by reversing the same, whereby the machine may be manually set for either addition or subtraction, without the necessity of disturbing such setting when making 5 a correction.

75. In combination, a typewriting mechanism including numeral keys, computing mechanism, means for enabling said keys to control said computing mechanism, a key 10 having means to break the connection between said numeral keys and said computing mechanism, and a separate key for restoring the connection between said numeral keys and said computing mechanism.

76. The combination of numeral keys, computing devices, means to coöperate with said keys to operate said computing devices *seriatim* at the operations of the keys, and a carry-over mechanism for said computing 20 devices, said carry-over mechanism including an assisting device effective at the operations of the numeral keys.

77. In a computing machine, the combination with computing devices, of key-controlled means for computing upon said devices, and a tens-carrying mechanism including a power operated assisting device other than the wheels themselves to relieve the wheels of part of the work of carrying 30 over; means being provided for effecting a reversal of the movement of the wheels and of the assisting device, for the purpose of subtracting.

78. The combination with a typewriting machine having a power-driven carriage and also having numeral keys, of a computing mechanism controlled by said numeral keys and including tens-carrying mechanism, said tens-carrying mechanism including an assisting or boosting device which is operated 40 by the carriage driving power.

79. The combination with a typewriting machine having a power-driven carriage and also having numeral keys, of a computing mechanism controlled by said numeral keys and including tens-carrying mechanism, said tens-carrying mechanism including an assisting or boosting device which is operated by the carriage driving power, means being 50 provided for effecting a reversal of the computing device and of the assisting mechanism for subtracting.

80. The combination with a series of computing wheels, of means actuated by each 55 computing wheel at a predetermined point in its rotation for shifting the next computing wheel one-tenth of a revolution in a direction determined by the character of computation, for the purpose of transferring tens, and an assisting mechanism arranged to operate said means to effect the complete transfer.

81. The combination with a series of computing wheels, of a master wheel for actuating 65 said computing wheels individually, and

means next adjacent said master wheel operative to actuate said computing wheels individually to correct an error in a computing wheel just operated.

82. The combination with a series of computing wheels, of a master wheel for actuating said computing wheels, a shaft for said master wheel, a sleeve loosely mounted on said shaft, a member on said sleeve adapted to actuate said computing wheels to make 75 a correction, and means for rotating said sleeve.

83. The combination with a set of totalizing wheels, of a set of numeral keys, means to coöperate with said keys to turn said 80 wheels *seriatim*, dogs normally engaging said wheels to lock them against rotation, and means for unlocking said dogs by the actuation of said keys.

84. The combination with a series of computing wheels, of locking means individual to each of said computing wheels, keys to release the locking means and rotate the wheels, correction mechanism for turning said computing wheels independently of said 90 keys individually to correct an error, and means operated at the actuation of said correction mechanism to release the locking means corresponding to the computing wheel to be turned by said correction mechanism. 95

85. The combination with a series of computing wheels, of a master wheel coöperating individually with each of said computing wheels to run up numbers thereon, means individual to each computing wheel 100 for initiating a carry-over operation, means actuated by said first-mentioned means for carrying one complete revolution of each computing wheel so as to cause a partial revolution of the next adjacent computing wheel, and power-driven assisting means for driving said last-mentioned means the remaining distance necessary to complete the carry-over operation, said power-driven assisting means being effective to effect the 105 completion of a carry-over operation to all computing wheels of higher denomination than the one with which the master wheel operates. 110

86. The combination with a series of computing wheels, of computing mechanism for running up numbers in said computing wheels, a series of numeral keys for controlling computing actions of said computing mechanism, tens-carrying mechanism for said computing wheels, and a source of power outside of said keys for driving said tens-carrying mechanism; said tens-carrying mechanism and said source of power both brought into play at the striking of said 115 numeral keys. 120

87. The combination with a series of computing wheels, of a master wheel for driving said computing wheels individually, a traveling carriage enabling a relative movement 130

between said computing wheels and said master wheel so that said master wheel will coöperate *seriatim* with said computing wheels, a series of numeral keys for controlling the running up of numbers into said computing wheels and the step-by-step movements of said traveling carriage, and tens-carrying mechanism for carrying over between adjacent computing wheels at the passing between "9" and "0," said tens-carrying mechanism including devices brought into play at the step-by-step movements of said carriage.

88. The combination with a series of computing wheels, of a series of numeral keys for controlling the running up of numbers in said computing wheels, a master wheel for running up numbers individually into said computing wheels, a traveling carriage for controlling the relative movement between said master wheel and said computing wheels, whereby said master wheel may coöperate *seriatim* with said computing wheels, and a tens-carrying mechanism including devices brought into play during a letter-feeding movement of said carriage.

89. The combination with a series of computing wheels, of a master wheel arranged to coöperate *seriatim* with said computing wheels to run up numbers therein, and a power-driven carry-over mechanism for said computing wheels effective at the operation of said master wheel to turn over between "9" and "0" all computing wheels of higher denomination simultaneously with the running up of a digit in any computing wheel effecting a turn over between "9" and "0."

90. The combination with a series of computing wheels, of computing mechanism including numeral keys, for running up numbers in said computing wheels digit by digit, carry-over mechanism for said computing wheels, and an assisting or boosting mechanism effective at the operation of said keys and simultaneously with the running up of a single digit in any computing wheel to aid in the completion of a carry-over operation started by the computing wheel having a digit run up therein, for all computing wheels of higher denomination.

91. The combination with a series of computing wheels, of means for running up numbers in said computing wheels digit by digit, tens-carrying mechanism for said computing wheels, and a boosting device driven from a source other than said computing wheels to assist in the carry-over operation, said boosting device being effective upon the turning of each computing wheel to zero position and before the running up of the next digit.

92. The combination with a series of computing wheels, of means for running up numbers in said computing wheels digit by

digit, a tens-carrying mechanism for said computing wheels, and a boosting device for said tens-carrying mechanism coming into play automatically upon the turning of each of said computing wheels to zero position.

93. The combination with a set of computing keys, and a plurality of computing wheels, one for each denomination to be computed, of locking means individual to each wheel, means to enable each key to release the wheels, mechanism for returning all of the wheels to zero, and releasing means actuatable by and simultaneously with said zero mechanism to release all of said wheels simultaneously.

94. The combination with a plurality of computing trains, one for each denomination to be computed, of numeral keys to operate said trains, locking means individual to each train, said means releasable by said keys, zero mechanism for returning all of said trains to zero, and releasing means brought into play simultaneously with the actuation of said zero mechanism to release all of said locking means to enable the return of said trains to zero.

95. The combination with a computing mechanism, of a series of numeral keys, numeral key-controlled valuating mechanism for determining the extent of actuation of said computing mechanism by said numeral keys, said valuating mechanism including a rotary index wheel or controller, a rotary escapement driven by said index wheel, and key-controlled means for controlling said rotary escapement.

96. The combination with a computing mechanism, of a series of numeral keys, a key-controlled rotary index wheel or controller for determining the extent of movement of said computing mechanism to correspond with the numeral key actuated, a rotary escapement driven by said controller and having a definite rotation at each movement of said controller, and key-operated means for controlling said escapement.

97. The combination with a computing mechanism, of a series of numeral keys, a controller to determine the extent of actuation of said computing mechanism to correspond with the numeral key actuated, a rotary escapement driven by said controller and normally holding the same against movement, and means common to the numeral keys for releasing said escapement.

98. In an apparatus of the character described, the combination of a computing shaft, a rotary controller, a source of power, mechanism whereby said computing shaft and rotary controller are both rotated from said source of power, keys to control the extent of rotation of said controller, and shiftable means between said controller and said computing shaft for reversing the di-

rection of rotation of the computing shaft relatively to the direction of rotation of the controller, to enable the controller, when turning in one direction, to effect either 5 addition or subtraction by means of said computing shaft, to an extent determined by the operated key.

99. The combination with a typewriting machine having a series of numeral keys, of 10 a computing attachment for said machine coöperable with said keys and including a registering mechanism, power mechanism operating said registering mechanism, means operable by said keys for governing 15 said power mechanism, said governing means including a universal bar operable by every key, and means for breaking and restoring the connections between said numeral keys and said governing means.

100. The combination with a typewriting machine having a series of numeral keys, of a computing attachment for said machine coöperable with said keys so as to be controlled thereby and comprising computing 25 mechanism capable of performing a variety of different types of computations, power mechanism for operating said computing mechanism, power-governing means coöperable with said keys, said governing means including a universal bar operable by every key, and means for breaking and restoring the connections between said numeral keys and said governing means.

101. The combination with a typewriting 35 machine, including a traveling carriage, of a series of computing wheels, said computing wheels being so numerous as to have a capacity of several complete adding zones for each run of the typewriter carriage, carry- 40 over mechanism extending the full length of said series of computing wheels so as to be operable to carry between any computing wheel in a series to the next adjacent computing wheel, and assisting driving means 45 for said carry-over mechanism distinct from said computing wheels for relieving the computing wheels of a part of the burden of carrying from one wheel to the next.

102. In an apparatus of the character de- 50 scribed, the combination of a series of computing devices, means for imparting rotary motion thereto, numeral keys for controlling said computing devices, and means for "carrying" from one device to the next at 55 the operation of said keys, comprising a transfer shaft, and means for imparting to said shaft a rotation independent of the movement of the computing devices.

103. In an apparatus of the character de- 60 scribed, the combination of a numeral key, a series of computing wheels, a computing shaft, means dependent upon the operation of the numeral key for rotating said shaft, means for "carrying" from one computing 65 means to the next, and means for rotating

the same independently of said computing shaft.

104. In an apparatus of the character de- 70 scribed, the combination of a series of computing wheels, numeral keys for controlling the same, transfer wheels for "carrying" from one computing wheel to the next, auxiliary transfer wheels meshing with the computing wheels, a transfer shaft, and means effective during the operation of the keys for 75 causing said shaft to engage the auxiliary transfer wheels to sufficiently complete the rotation of the same when partly turned by the computing wheels.

105. The combination with a series of 80 computing wheels, of a series of numeral keys, means under the control of the keys for driving said computing wheels one by one as the numeral keys are actuated, a carry-over mechanism for said computing 85 wheels effective at the striking of each numeral key to enable the carrying of tens between higher and lower denominations of said computing wheels, and a drive for said carry-over mechanism independent of the 90 extent of movement of said computing wheels.

106. The combination with a series of computing wheels, of a series of numeral keys, means for driving said computing 95 wheels one by one as the numeral keys are actuated, a carry-over mechanism for said computing wheels acting for the running in of each digit, to enable the carrying of tens between higher and lower denominations of said computing wheels, and a drive for said carry-over mechanism rotating amounts independent of the particular numeral keys actuated.

107. In an apparatus of the character de- 100 scribed, the combination, with a typewriting mechanism including a carriage, of a series of computing wheels, a computing shaft therefor, a transfer shaft, transfer mechanism carried by said shaft and adapted to transfer from one computing wheel to the next, and means connected to said carriage for rotating said transfer shaft.

108. The combination with a set of numeral keys and a succession of computing 115 wheels controlled thereby, of a tens-carrying device controlled by one wheel to effect advance of the next higher wheel, and a power-rotated member to engage said tens-carrying device and actuate the same at the operation of said keys, each tens-carrying device being rotatable by the wheel of lower denomination, and being moved into engagement with the power-rotated member to be rotated thereby.

109. The combination of computing wheels and carry-over devices with a reversing mechanism for causing the computing wheels to either add or subtract, a power rotated member to assist at the carry-over opera- 120 125 130

tion, and means to cause the power rotated member to reverse the direction of its rotation.

110. The combination with a plurality of 5 numeral keys, of a computing mechanism, a source of power for actuating said computing mechanism, the actuation of said computing mechanism by said source of power being controlled by said numeral keys, and 10 a key for rendering said numeral keys incapable of causing said source of power to actuate said computing mechanism.

111. The combination with a digit wheel and master-wheel mechanism, of a rotary 15 controller or indexing wheel connected to the master wheel, a source of power for driving the master wheel to the extent permitted by said controller, a series of indexing devices on said controller, numeral keys for 20 setting said indexing devices to limit the movements of the controller and master wheel, and means controlled by the keys to permit step-by-step advance of the controller to different extents determined by the set 25 indexing devices.

112. The combination with a digit wheel and master wheel mechanism, of a rotary controller or indexing wheel connected to the master wheel, a source of power for 30 driving the master wheel to the extent permitted by said controller, a series of indexing devices on said controller, numeral keys for setting said indexing devices to limit the movements of the controller and master 35 wheel, means controlled by the keys to permit variable step-by-step advance of the controller to different extents determined by set indexing devices, and means for enabling said indexing wheel to restore the set 40 pins to their normal position.

113. The combination with a digit wheel and master wheel mechanism, of a rotary controller or indexing wheel connected to the master wheel, a motor for driving the 45 master wheel to the extent permitted by said controller, a series of settable indexing devices on said controller, numeral keys, means connected with said numeral keys for setting said indexing devices, a pinion rotatable 50 by the set indexing devices, and means controlled by the keys for permitting said pinion to be advanced by said controller.

114. The combination with a digit wheel and a master wheel mechanism, of a normally stationary rotary controller connected 55 to the master wheel having a series of settable pins, a pinion to engage or mesh with said pins, a motor whereby the master wheel, controller and pinion are driven, numeral keys having means to control the setting of 60 said pins and thereby determine the extent of rotation of said controller to be effected by said motor, and means under the control of the keys to permit the controller and pinion to be driven by the motor.

115. The combination of a series of digit wheels, a master wheel therefor, means for enabling the master wheel to drive the digit wheels *seriatim*, carry-over devices whose movements are initiated by the digit wheels, 70 and a revolute driving device extending along the carry-over devices and having means to act thereon concomitantly with the operation of said master wheel, to insure the completion of the operation of said carry- 75 over devices.

116. The combination with a series of digit wheels, operable either forwardly or backwardly, for effecting addition or subtraction, of carry-over devices for said 80 wheels, including means whereby the individual wheels may initiate the carry-over operations in either direction for addition or subtraction, and power-driven means to complete the carry-over operations; said power-driven means being also reversible as to direction of operation, so that it may be effective in either addition or subtraction, as required.

117. The combination of a series of digit 90 wheels, a master wheel therefor, means for enabling the master wheel to drive the digit wheels *seriatim*, carry-over pinions whose movements are initiated by the digit wheels, and a revolute driver extending along the 95 pinions to act thereon to insure the completion of the rotative movements thereof concomitantly with the operation of said master wheel.

118. In a combined typewriting and computing machine, the combination with a typewriter carriage movable into and out of an adding zone, and numeral keys, of computing mechanism, means to enable the keys to control the letter-feeding movements 100 of the carriage, individual connections from said keys to said computing mechanism, printing types controlled by said keys, and means operable manually at the will of the operator for shifting all of said individual 110 connections simultaneously, to render the computing mechanism inoperable by the keys.

119. The combination with power-driven computing wheels, of a revolute indexing 115 device therefor having a circular row of indexing members, a set of numeral keys, and a stationary set of indexing devices operable by said keys and having a yielding construction to enable them to clear the unset 120 revolving indexing devices independently of the return of the keys to normal positions.

120. The combination of mechanical indexing devices, a set of numeral keys, mechanical connections extending from said 125 keys to said indexing devices and including means for automatically disconnecting the indexing devices from the keys, to permit movements of the indexing devices independently of the return of the keys, and 130

means for automatically reestablishing the connections between the keys and the indexing devices.

121. The combination of mechanical indexing devices, a set of numeral keys, mechanical connections extending from said keys to said indexing devices and including means for automatically disconnecting the indexing devices from the keys during the down-strokes of the keys, and means for automatically reconnecting the keys with the indexing devices during the return strokes of the keys.

122. The combination with a computing mechanism comprising a set of wheels and means for operating said wheels *seriatim*, of a set of numeral keys to control said computing mechanism, manually-shiftable means for setting said computing mechanism to either add or subtract at the operation of the keys, and means for effecting corrections on said wheels individually while the computing mechanism remains manually set for either addition or subtraction, said correction-effecting means including a member manually movable in one direction for addition and in the opposite direction for subtraction, independently of said manually-shiftable means.

123. The combination with a set of numeral keys and a computing mechanism, comprising a set of wheels and means for enabling the keys to control the operation thereof, of manually adjustable main reversing means for said wheels, and manually controllable auxiliary means for enabling the operative to turn the wheels oppositely to the direction for which they are set by said main reversing means.

124. The combination of a series of computing wheels, rotating means for said wheels, a series of numeral keys, means to enable the keys to control the rotation of the computing wheels *seriatim*, individual locks for said computing wheels, means to enable any key to release any lock, and means dependent upon the operation of said rotating means for restoring the released lock.

125. The combination of a series of computing wheels, rotating means for said wheels, a series of numeral keys, means to enable the keys to control the rotation of the computing wheels *seriatim*, individual locks for said computing wheels, means to enable any key to release any lock, means dependent upon the operation of said rotating means for restoring the released lock, carry-over devices for said computing wheels, and means to enable said carry-over devices to operate to release the wheels of higher denominations.

126. The combination of a set of digit wheels, means normally locking the wheels against rotation, a set of numeral keys, mechanism controlled by said keys for both

releasing the wheels and operating them *seriatim*, and means automatically called into action at the conclusion of the rotation of any wheel for relocking the same independently of the keys.

127. The combination with a set of computing wheels and a master wheel therefor, a variably movable indexing member for controlling the rotation of said master wheel, keys, and means for enabling the keys to control said indexing member, of means normally locking said wheels against rotation, means extending to said keys to enable any thereof to unlock any of said wheels for operation by said master wheel, and means dependent upon the conclusion of the operation of said variably movable indexing member for re-locking the operated wheel independently of the keys.

128. The combination with a set of computing wheels and a master wheel therefor, a variably movable indexing member for controlling the rotation of said master wheel, keys, and means for enabling the keys to control said indexing member, of means normally locking said wheels against rotation, means extending to said keys to enable any thereof to unlock any of said wheels for operation by said master wheel, means dependent upon the conclusion of the operation of said variably movable indexing member for relocking the operated wheel independently of the keys, said indexing member comprising a wheel, and a source of power connected to said indexing member and to said master wheel.

129. The combination with a set of computing wheels and a master wheel therefor, a variably movable indexing member for controlling the rotation of said master wheel, keys, and means for enabling the keys to control said indexing member, of means normally locking said wheels against rotation, means extending to said keys to enable any thereof to unlock any of said wheels for operation by said master wheel, a latch to hold the wheel unlocked, and means to enable said variably movable indexing member to release said latch.

130. The combination of a series of computing wheels, a series of carry-over trains therefor; each train including both a pinion for driving the wheel of higher denomination and means to operate said pinions, rotating means for said computing wheels, a series of numeral keys, means, including a carriage, to enable the keys to control the rotation of the computing wheels *seriatim*, individual locking dogs for the computing wheels, means to enable any key to release any locking dog, means dependent upon the operation of said rotating means for restoring the locking dog of the operated computing wheel, and means to enable any of said carry-over pinions to cause the release and

restoration of the locking dog of the higher computing wheel.

131. The combination of a series of computing wheels, a series of carry-over trains therefor; each train including both a pinion for driving the wheel of higher denomination and means to operate said pinions, rotating means for said computing wheels, a series of numeral keys, means, including a carriage, to enable the keys to control the rotation of the computing wheels *seriatim*, individual locking dogs for the computing wheels, means to enable any key to release any locking dog, means dependent upon the operation of said rotating means for restoring the locking dog of the operated computing wheel, means to enable any of said carry-over pinions to cause the release and restoration of the locking dog of the higher computing wheel, and auxiliary means extending along the series of carry-over trains for engaging said trains to assist in the operation thereof.

132. The combination of a series of computing wheels, rotating means therefor, a series of numeral keys, means to enable the keys to control the rotation of the computing wheels *seriatim*, individual locking dogs for the computing wheels, means to enable any key to release any locking dog, means to latch the released locking dog, and means dependent upon the operation of the wheel-rotating means for releasing the latch and restoring said locking dog.

133. The combination of a series of computing wheels, rotating means therefor, a series of numeral keys, means to enable the keys to control the rotation of the computing wheels *seriatim*, individual locking dogs for the computing wheels, means to enable any key to release any locking dog, means to latch the released locking dog, means dependent upon the operation of the wheel-rotating means for releasing the latch and restoring said locking dog, carry-over devices for said computing wheels, and means to enable said carry-over devices to release said locking dogs and permit the latter to re-lock their respective wheels.

134. The combination of a series of computing wheels and carry-over devices, said computing wheels normally locked, rotating means for said wheels, a series of numeral keys, means, including a carriage, to enable the keys to control the rotation of the wheels *seriatim*, means directly connected with the keys and dependent upon the operation thereof for releasing the computing wheels *seriatim*, and means dependent upon the operation of said rotating means, for restoring the locked condition of the operated computing wheel.

135. The combination of a series of computing wheels and carry-over devices, said computing wheels normally locked, rotat-

ing means for said wheels, a series of numeral keys, means, including a carriage, to enable the keys to control the rotation of the wheels *seriatim*, means directly connected with the keys and dependent upon the operation thereof for releasing the computing wheels *seriatim*, and means dependent upon the operation of said rotating means, for restoring the locked condition of the operated computing wheel; each of said carry-over devices effective to control the release and restoration to locked condition of the wheel of higher denomination.

136. The combination of a series of numeral keys, computing wheels controllable *seriatim* thereby, carry-over trains, each train comprising a pinion device partially movable by the computing wheel of lower denomination, a shaft extending along said pinions and having means to engage and rotate the same when they have been moved by the computing wheels, and means to operate the shaft at each computing-wheel operation.

137. The combination of a series of numeral keys, computing wheels controllable *seriatim* thereby, carry-over trains, each train comprising a pinion device partially movable by the computing wheel of lower denomination, a shaft extending along said pinions and having means to engage and rotate the same when they have been moved by the computing wheels, a source of power, and connections extending from said source of power to said shaft, to operate the latter at the operations of said numeral keys.

138. The combination of a series of numeral keys, computing wheels controllable *seriatim* thereby, carry-over trains for said computing wheels, power-driven means for operating said computing wheels at the operations of said keys, and power-driven means for concomitantly operating said carry-over trains.

139. The combination of a carriage, a series of numeral keys to control said carriage, computing wheels, means to coöperate with said keys and said carriage to control the operation of the wheels, carry-over trains, a shaft extending along said carry-over trains and having means to engage and drive the same when they have been started by the computing wheels, and means to operate said shaft.

140. The combination of a carriage, a series of numeral keys to control said carriage, computing wheels, means to coöperate with said keys and said carriage to control the operation of the wheels, a series of carry-over trains movable by the computing wheels, and means extending along said series of carry-over trains and common thereto, to engage and drive any of said trains when they have been started by the computing wheels.

141. The combination of a carriage, a series of numeral keys to control said carriage, computing wheels, means to coöperate with said keys and said carriage to control the operation of the wheels, a series of carry-over trains movable by the computing wheels, means extending along said series of carry-over trains and common thereto, to engage and drive any of said trains when they have been started by the computing wheels, means for propelling said carriage, and means connected to said propelling means for operating said train-driving means at each advance letter-feeding movement of the carriage.

142. The combination of a carriage, a series of numeral keys to control said carriage, computing wheels, means to coöperate with said keys and said carriage to control the operation of the wheels, a series of carry-over trains movable by the computing wheels, means extending along said series of carry-over trains and common thereto, to engage and drive any of said trains when they have been started by the computing wheels, means for propelling said carriage, and means connected to said propelling means for operating said train-driving means at the return movement of the carriage.

143. The combination of a carriage, a series of numeral keys to control said carriage, computing wheels, means to coöperate with said keys and said carriage to control the operation of the wheels, a series of carry-over trains movable by the computing wheels, means extending along said series of carry-over trains and common thereto, to engage and drive any of said trains when they have been started by the computing wheels, means for propelling said carriage, and means connected to said propelling means for operating said train-driving means at both the advance and return movements of the carriage.

144. The combination with a set of computing wheels, a master member, and means for effecting relative step-by-step movement between the master member and the computing wheels for operating the latter *seriatim*, of a carry-over mechanism including an auxiliary power-actuated device coöperating any of said wheels to turn the wheel of next higher denomination, and means for reversing said master member and said auxiliary device.

145. The combination with a set of computing wheels, a reversible master wheel for operating the same *seriatim*, and means for effecting relative step-by-step movement between the master wheel and the computing wheels, of means for carrying over from each wheel to the next, comprising an interponent called into action by the wheel of low denomination and having means to actu-

ate the wheel of higher denomination, and a reversible auxiliary prime moving device to act upon said interponent, concomitantly with the operation of the master wheel, to cause said interponent to move the wheel of higher denomination.

146. The combination of a set of digit wheels, a master wheel for operating the digit wheels *seriatim*, means being provided for effecting relative step-by-step movement between the master wheel and the digit wheels, means for rotating the master wheel variably, means for reversing the direction of rotation of the master wheel, a set of carry-over devices for said digit wheels, and reversible means extending along said set of carry-over devices for assisting in the carry-over operations concomitantly with the operation of the master wheel in either direction.

147. The combination of a set of digit wheels, a master wheel for operating the digit wheels *seriatim*, means being provided for effecting relative step-by-step movement between the master wheel and the digit wheels, means for rotating the master wheel variably, means for reversing the direction of rotation of the master wheel, a set of carry-over devices for said digit wheels, a revolvable drive shaft extending along the set of digit wheels and carry-over devices, and having means to assist at carry-over operations, and means to revolve said shaft in either direction concomitantly with the operation of the master wheel in corresponding direction.

148. The combination of numeral keys, reversible computing devices, means to coöperate with said keys to operate said computing devices *seriatim* and either forwardly or backwardly at the operations of the keys, and reversible carry-over mechanism for said computing devices, said carry-over mechanism including a reversible assisting device effective at the operations of the numeral keys.

149. The combination of a set of digit wheels, a master wheel for operating the digit wheels *seriatim*, means being provided for effecting relative step-by-step movement between the master wheel and the digit wheels, means for rotating the master wheel variably, means being provided for normally locking the digit wheels against rotation, means for releasing each wheel at the operation of the master wheel, a set of carry-over trains for said digit wheels, said carry-over trains including means to unlock the digit wheels, and a revolvable device extending along the set of carry-over trains to act directly thereon at the operation of the master wheel, for assisting in the operations of said carry-over trains.

150. The combination of a set of digit wheels, a master wheel for operating the

digit wheels *seriatim*, means being provided for effecting relative step-by-step movement between the master wheel and the digit wheels, means for rotating the master wheel 5 variably, means being provided for normally locking the digit wheels against rotation, means for releasing each wheel at the operation of the master wheel, a set of carry-over trains for said digit wheels, said carry-over trains including means to unlock the digit wheels, and a revoluble device extending along the set of carry-over trains to act directly thereon at the operation of the master wheel, for assisting in the operations of 10 said carry-over trains; said master wheel and said assisting means being reversible for performing subtraction.

151. The combination of a set of digit wheels, a master wheel for operating the 20 digit wheels *seriatim*, means being provided for effecting relative step-by-step movement between the master wheel and the digit wheels, means for rotating the master wheel variably, means being provided for normally locking the digit wheels against rotation, means for releasing each wheel at the operation of the master wheel, a set of carry-over trains for said digit wheels, said carry-over trains including means to unlock the 25 digit wheels, a revoluble device extending along the set of carry-over trains to act directly thereon at the operation of the master wheel, for assisting in the operations of said carry-over trains, and means dependent 30 upon the completion of the operation of the master wheel, for restoring the released locking means.

152. The combination of a totalizer, a master member for operating said totalizer, 40 a carriage for effecting relative step-by-step movements between the master member and the totalizer, numeral keys to control the carriage, means to enable said numeral keys to control the movements of said totalizer 45 effected by said master member, a spring to drive said master member, and means to enable the return movements of said carriage to retension said spring.

153. The combination of a set of digit 50 wheels, a master wheel therefor, means for effecting relative step-by-step movements between the master wheel and the digit wheels, a source of power for driving the master wheel, an indexing device for controlling the rotation of the master wheel, key-driven means for controlling said indexing device, and means between the indexing device and the master wheel for reversing the direction of rotation of the latter at 55 the operation of the indexing device.

154. The combination of a series of numeral keys, reversible computing wheels controllable *seriatim* thereby, reversible carry-over trains, each train comprising a pinion 60 device partially movable by the computing

wheel of lower denomination, a shaft extending along said pinions and having means to engage and rotate the same in either direction when they have been moved by the computing wheels, and means to reverse the direction of operation of the shaft. 70

155. The combination of a series of numeral keys, reversible computing wheels controllable thereby, reversible carry-over trains, each train comprising a pinion device 75 partially rotatable by the computing wheel of lower denomination, a shaft extending along said pinions and having means to engage and rotate the same when they have been partially rotated by the computing 80 wheels, a source of power, and reversible connections extending from said source of power to said shaft, to operate the latter in either direction.

156. The combination of a series of numeral keys, reversible computing wheels controllable *seriatim* thereby, carry-over trains for said computing wheels, power-driven reversible means for operating said computing wheels at the operations of said 90 keys, and power-driven reversible means for concomitantly operating said carry-over trains.

157. The combination of a carriage, a series of numeral keys to control said carriage, reversible computing wheels, reversible means to coöperate with said keys and said carriage to control the operation of the wheels, a series of carry-over trains initially movable either forwardly or backwardly by 100 the computing wheels, and reversible means extending along said series of carry-over trains and common thereto to engage and drive any of said trains either forwardly or backwardly when they have been started by 105 the computing wheels.

158. The combination of a carriage, a series of numeral keys to control said carriage, reversible computing wheels, reversible means to coöperate with said keys and 110 said carriage to control the operation of the wheels, a series of carry-over trains initially movable either forwardly or backwardly by the computing wheels, reversible means extending along said series of carry-over trains and common thereto to engage and drive any of said trains either forwardly or backwardly when they have been started by the computing wheels, means for propelling said carriage, and reversible 115 means connected to said propelling means for operating said train-driving means at each advance letter-feeding movement of the carriage.

159. The combination of a carriage, a series of numeral keys to control said carriage, reversible computing wheels, reversible means to coöperate with said keys and said carriage to control the operation of the wheels, a series of carry-over trains 120

130

initially movable either forwardly or backwardly by the computing wheels, reversible means extending along said series of carry-over trains and common thereto to engage and drive any of said trains either forwardly or backwardly when they have been started by the computing wheels, means for propelling said carriage, and reversible means connected to said propelling means for operating said train-driving means either forwardly or backwardly at the return movement of the carriage.

160. The combination of a carriage, a series of numeral keys to control said carriage, reversible computing wheels, reversible means to coöperate with said keys and said carriage to control the operation of the wheels, a series of carry-over trains initially movable either forwardly or backwardly by the computing wheels, reversible means extending along said series of carry-over trains and common thereto to engage and drive any of said trains either forwardly or backwardly when they have been started by the computing wheels, means for propelling said carriage, and means connected to said propelling means for operating said train-driving means either forwardly or backwardly at both the advance and return movements of the carriage.

161. The combination of a set of reversible digit wheels, reversible means for operating the digit wheels, means being provided for normally locking the digit wheels against rotation in either direction, means for releasing said wheels to operate either forwardly or backwardly, a set of reversible carry-over trains for said digit wheels, said carry-over trains including means to unlock the digit wheels when either addition or subtraction is being performed, and a reversible revolute device extending along the set of carry-over trains to act directly thereon, for assisting in the operations of said carry-over trains when either adding or subtracting.

162. The combination of a set of reversible digit wheels, a reversible master wheel for operating the digit wheels *seriatim*, means being provided for effecting relative step-by-step movement between the master wheel and the digit wheels, reversible means for rotating the master wheel variably, means being provided for normally locking the digit wheels against rotation in either direction, means for releasing each wheel at the operation of the master wheel either forwardly or backwardly, a set of reversible carry-over trains for said digit wheels, said carry-over trains including means to unlock the digit wheels, and a revolute auxiliary device extending along the set of carry-over trains to act directly thereon at the operation of the master wheel, for assisting in the operation of said carry-over

trains; said master wheel and said assisting means being reversible for performing subtraction.

163. The combination of a set of reversible digit wheels, a reversible master wheel for operating the digit wheels *seriatim*, means being provided for effecting relative step-by-step movement between the master wheel and the digit wheels, reversible means for rotating the master wheel variably, means being provided for normally locking the digit wheels against rotating in either direction, means for releasing each wheel at the operation of the master wheel either forwardly or backwardly, a set of reversible carry-over trains for said digit wheels, said carry-over trains including means to unlock the digit wheels, a revolute auxiliary device extending along the set of carry-over trains to act directly thereon at the operation of the master wheel, for assisting in the operation of said carry-over trains; said master wheel and said assisting means being reversible for performing subtraction, and means dependent upon the completion of the operation of the master wheel in either direction, for restoring the released locking means.

164. The combustion of a set of reversible totalizer wheels, numeral keys, means to operate the totalizer wheels to the extents determined by the keys, devices on said totalizer wheels to initiate carry-over operations, carry-over trains initially rotatable by said initiating devices in either direction, a shaft extending along said trains to complete the rotation thereof in either direction, and reversible means for driving said shaft in either direction.

165. The combination with a series of reversible computing wheels, of a reversible master wheel to coöperate *seriatim* with said computing wheels, and a reversible power-driven carry-over mechanism effective at the operation of said master wheel, to turn over in either direction between "9" and "0" all computing wheels of higher denomination than that upon which the master wheel is acting.

166. The combination with a series of computing wheels, of means for running up numbers in said computing wheels digit by digit, tens-carrying mechanism for said computing wheels, a boosting device driven from a source other than said computing wheels to assist in the carry-over operation, said boosting device being effective upon the turning of each computing wheel to zero position and before the running up of the next digit, and devices shiftable to reverse the operation of the computing wheels and boosting device.

167. The combination with a series of computing wheels, numeral keys, and reversible means coöoperating with said keys

to effect the operation of said wheels *seriatim* as the keys are operated, of means for carrying tens from one wheel to the next, comprising a reversible interponent called 5 into action by a wheel of low denomination and having means to actuate in either direction a wheel of higher denomination, and an auxiliary reversible prime-moving device capable of acting in either direction at the operation 10 of any numeral key, to act upon said interponent to cause it to move or complete the movement of the wheel of higher denomination in either direction.

168. The combination with a series of 15 computing wheels, numeral keys, and reversible means to coöperate with said keys for effecting the operation of said wheels *seriatim*, of a reversible carry-over mechanism including a reversible auxiliary power- 20 actuating device coöperative with any of said wheels at the operation of any numeral key, to turn in either direction the wheel of next higher denomination.

169. The combination with a series of 25 computing wheels, numeral keys, and reversible means coöperating with said keys to effect the operation of said wheels *seriatim* as the keys are operated, of means for carrying tens from one wheel to the next, 30 comprising a reversible interponent called into action by a wheel of low denomination and having means to actuate in either direction a wheel of higher denomination, an auxiliary reversible prime-moving device capable 35 of acting in either direction at the operation of any numeral key, to act upon said interponent to cause it to move the wheel of higher denomination in either direction; said auxiliary device extending along the series 40 of wheels and mounted for rotation, and shiftable means for controlling the direction of rotation of said auxiliary device to correspond with the direction in which the computing wheels are rotated at the operations 45 of the keys.

170. The combination of numeral keys, computing devices, means to coöperate with said keys to operate said computing devices *seriatim* at the operations of the keys, means 50 shiftable to reverse the direction of movement of said computing devices at the operations of the keys, and a reversible carry-over mechanism for said computing devices, said carry-over mechanism including a reversible assisting device effective at the operations 55 of the numeral keys.

171. The combination of a series of reversible computing wheels, reversible rotating means for said wheels, a series of numeral keys, means to enable the keys to control the extent of rotation of the computing wheels in either direction, individual locks for said computing wheels, means to release the locks, and means dependent 60 upon the operation of said rotating means

in either direction for restoring the released lock.

172. The combination of a series of reversible computing wheels, reversible rotating means for said wheels, a series of numeral keys, means to enable the keys to control the rotation of the computing wheels in either direction, individual locks for said computing wheels, means to release the locks, means dependent upon the operation of said 70 rotating means in either direction for restoring the released locks, reversible carry-over devices for said computing wheels, and means to enable said carry-over devices, when moving either forwardly or backwardly, to operate to release the wheels of higher denominations. 75

173. The combination of a set of reversible digit wheels, means normally locking the wheels against rotation, a set of numeral keys, mechanism controlled by said keys for both releasing the wheels and operating them *seriatim* either forwardly or backwardly, and means automatically called into action at the conclusion of the rotation of any wheel in either direction for relocking the same independently of the keys. 80

174. The combination with a set of computing wheels and a master wheel therefor, and a variably movable indexing member 95 for controlling the rotation of said master wheel, of shiftable means between said indexing member and said master wheel to enable the former to rotate the latter either forwardly or backwardly, keys, means for enabling the keys to control said indexing member, means normally locking said wheels against rotation, means extending to said keys to enable any thereof to unlock any of said wheels for operation by said master wheel, and means dependent upon the conclusion of the operation of said variably movable indexing member for re-locking the operated wheel independently of the keys 100 when either adding or subtracting. 105

175. The combination with a set of computing wheels and a master wheel therefor, and a variably movable indexing wheel for controlling the rotation of said master wheel, of shiftable means between said indexing 115 wheel and said master wheel to enable the former to rotate the latter either forwardly or backwardly, keys, means for enabling the keys to control said indexing wheel, means normally locking said computing wheels against rotation, means extending to said keys to enable any thereof to unlock any of said computing wheels for operation by said master wheel, means dependent upon the conclusion of the operation of said variably 120 movable indexing wheel for re-locking the operated computing wheel independently of the keys when either adding or subtracting, and a source of power connected to said indexing wheel and to said master wheel. 125

176. The combination of a series of reversible computing wheels, reversible rotating means therefor, a series of numeral keys, means to enable the keys to control the extent of rotation of the computing wheels, individual locking dogs for the computing wheels, means to release the locking dogs, means to latch the released locking dogs, and means dependent upon the operation of the wheel-rotating means in either direction, for releasing the latches and restoring the locking dogs.

177. The combination of a series of reversible computing wheels, reversible rotating means therefor, a series of numeral keys, means to enable the keys to control the extent of rotation of the computing wheels, individual locking dogs for the computing

wheels, means to release the locking dogs, means to latch the released locking dogs, means dependent upon the operation of the wheel-rotating means in either direction for releasing the latches and restoring the locking dogs, reversible carry-over devices for said computing wheels, and means to enable said carry-over devices, when operating either forwardly or backwardly, to release said locking dogs and permit the latter to re-lock their respective wheels.

In testimony whereof I have hereunto set my hand in the presence of two subscribing witnesses.

WALTER WRIGHT.
